UNITED STATES PATENT OFFICE

MAX C. MILLER, OF CUMBERLAND, RHODE ISLAND

KNITTING MACHINE

Application filed August 9, 1926, Serial No. 128,059. Renewed February 8, 1932.

My invention relates to flat full fashioned knitting machines.

The objects to be attained are to produce automatically a stocking very similar to that now produced on so-called Cotton frames. In machines of this type, the method of procedure is as follows: The setting up at the welt being performed manually after which the welt fabric is knitted by power, then manually turning the welt, after which the leg of the stocking is knitted by power to the point where the narrowing begins, at which time a group of transferring points at each side of the fabric lift off a group of loops 15 forming the edges of the fabric, and move said groups inwardly toward each other, one or two needles at a time, transferring the loops held by them back to the needles, thereby narrowing the fabric one or two needles at 20 a time at each side of the fabric, the narrowing taking place at some little distance inside the edges of the fabric. The fabric to the outside of the narrowing needles I will call the standing wales. This method of procedure continues until the ankle is reached, after which the needles forming the instep cease knitting, while the needles on each side of these instep needles continue knitting forming the heel flaps, which are at their 25 ends narrowed in the same manner as described for the leg narrowing, after which the stocking is cast from the machine.

This leg blank is now transferred manually to a series of points along the line of 35 the selvage formed on the inner side of the heel flaps and the course of loops across the instep. These points which are in a bar, then through manual manipulation, are caused to transfer the loops held thereon to a footing machine, upon which machine the foot is knitted. Directly after being so transferred, this 40 footing machine, which is also equipped with narrowing points, narrows the foot similar to the previous leg narrowing heretofore described. Knitting of the foot continues, followed by narrowing points going into operation that narrow the toe, after which the 45 stocking is cast from the footer. This I will call the complete stocking blank.

50 With the subsequent operations necessary

to fabricate this complete stocking blank into a tubular stocking we are not interested as the method for so doing is alike under the Cotton systems and the contemplated system. The contemplated complete stocking blank 55 having all the earmarks of a stocking above described, with the exception of not having a turned welt, also having a slightly different toe than is customarily made on present day Cotton frames.

This difference in the toe resides in the fact that no gussets are inserted between the top and underside of the toe, the new toe, however, being the same shape as the gusseted toe.

The primary difference in generic principle between the above described method and the contemplated method resides that in the former the stocking blank is shaped by narrowing and in the latter the shaping is accomplished through widening.

The principal difference in generic principles between the above described mechanical means and the contemplated means to accomplish the shaping is that in the former the standing wale loops are transferred from one group of needles to another group of needles, the loops, themselves, being moved through intermediary transfer points, whereas in the contemplated mechanical 75 means for shaping, the standing wale needles, with their loops are moved bodily outwardly, permitting the adding of needles, no intermediary devices being used, and no loops transferring takes place.

These mechanisms for loop transferring are in the Cotton and similar systems very delicate in manufacture and maintenance, requiring that an absolute register take place between the points and the needles, necessitating absolute mechanical building and movement accuracy, maintaining this accuracy throughout the life of the machine and necessitating a continued watchfulness, as to needle and transfer point straightness.

In the contemplated method, the standing wale needles carrying the standing wale loops, are themselves bodily stepped out, the only accuracy necessary is that suitable mechanism be provided to ensure the stand-

100

ing wale needles maintaining the gauge while in any of their various positions, needle straightness being not at all essential.

Another outstanding advantage of the contemplated method over the former method resides in that the foot is completed on the same machine that knits the leg and yet produces practically the same type of stocking as the latter. This is of great importance, as it eliminates the possibility of loop variation across the instep. This variation in the former method is brought about by the fact that the leg at this point is formed from yarn feeding from another bobbin, necessitating, to get any reasonable like appearance of loops, absolute like thickness, type and quality of the two yarns, absolute like wound bobbins, with absolute like tension and adjustment of sinkers, dividing sinkers, needle draw, take up tension and all points having to do with the forming of the loops, also, of course, necessitating great care and accuracy in the actual manual transferring of the leg blank to the footing machine.

While in the specific drawings herewith, only one section of the machine is shown and described, it is perfectly obvious that the parts are so co-ordinated and designed as to permit a multiplicity of sections to be used in the complete machine and that in their operation as a multiple section machine expansion and contraction and wear of parts, which operates to a great detriment in present systems, will have no effect and that there is no great accuracy required, nor will wear develop, in the movements of widening in this machine as is in the former system, where screw shafts and similar mechanisms must, by a partial rotation, accurately register elements, one with the other.

Through the use of the contemplated machine, it will be possible to automatically, without stopping, produce complete full fashioned stocking blanks and that with very little skill on the part of the operators and without laboring under the insurmountable difficulties as with present systems.

The contemplated machine incorporates, by preference, although not necessarily, in its system, the jack sinkers, dividing sinkers and en-masse needle movement, the one outstanding different being in the construction of the elements that knock over the formed loops and hold down the fabric as the needles rise for the next course.

With the Cotton and similar systems, it is possible to widen fabric having standing wales but only through the use of transferring points and similar mechanisms. When machines of this type are used for so widening, a hole results at the point in the fabric in which the widening needle appears for the first time. This hole is caused by the sinkers feeding an amount of yarn equal to the amount fed to all other needles, whereas this

added needle in the first course in which it appears, does not form a loop, not doing so until the next course.

In the contemplated system, a sinker on both sides of any widening needle, are in the first course in which such needle appears, caused to become inactive, no yarn being kink fed to this needle. The inactive sinkers going into action on the next course, in which the widening needle forms a regular loop although said sinkers could remain inactive if found desirable for another course, in order to make even a more prominent pucker.

This feature of the invention is not limited in its use to the type of machine here disclosed, but can well be used in existing types of widening Cotton frames.

The mode of operation of the contemplated machine is as follows: Yarn is fed to the needles, of which the proper number to form the tip of the toe, including among them, standing wale needles and body wale needles, are active, the toe being gradually widened by the standing wale needles stepping outwardly on both sides, body wale needles being inserted as the standing wale needles are stepped out, needles at the same time being added one at a time to the stepping out needles, until the width of the desired foot is attained, after which the foot is knitted, followed by the standing wale needles stepping outwardly with body wale needles being added, until the desired widened width of the foot has been attained. After which the needles forming the sole portions, which are on both sides of a group of needles forming the instep portion, alone continue knitting, with the instep portion holding their loops but not knitting. The sole loops so formed constitute ravel loops. Just previous to the formation of these ravel loops, the sole needles should, by preference, form slightly longer loops, to aid in later transferring and looping these sole portions to the inner selvage loops of the subsequently knitted heel flaps. After which these sole portions are cast off the needles, the instep needles continuing to hold their loops.

A new fabric is now set up on the sole needles, the first course preferably being knit on alternate needles as illustrated in Fig. 26 to form ravel on the narrow ends of the heel flaps which are later to be looped together in the usual manner. After knitting sufficient ravel, these sole needles which are now heel flap needles, knit the loose course, after which the standing wale needles which form part of these heel flap groups, are stepped outwardly to widen the heel flaps, new body wale needles being inserted until a sufficient width has been attained, after which the length required for the heel flaps is knitted. Throughout this portion of the knitting the instep needles have remained inactive holding their loops. Upon having knitted the required length of

widened heel flaps, the instep needles again go into action, in conjunction with the two groups of heel flap needles on either side thereof, thereby forming the ankle fabric. 5 This width of fabric is continued until it is desired to widen the leg, at which time the standing wale needles on either edge of the fabric, step outwardly, new body wale needles being inserted, until a sufficient width of fabric has been attained. This width is maintained throughout the remainder of the stocking. 10 Top leg widening can be put in if found desirable. After a point has been reached where the required length of stocking has been knitted, all the loops are cast from the needles with, by preference, the exception of those body wale needles that will, in the next stocking, form the central portion of the toe tip, although all the needles can cast off their loops, in which case a set up, preferably on alternate needles, would be made for the tip of the toe. The standing wale needles, upon casting off their loops, fall inwardly, preferably in one movement, to take up their positions, preparatory to knitting the next stocking.

My invention is fully shown and described in the following specifications and 18 sheets of drawings, in which Fig. 1 shows the completed stocking after it has been looped and sewed: Fig. 2 is a plan view of the needles holding loops of ordinary fabric: Fig. 3 is a plan view of the needles holding loops, showing the standing wale needles with loops stepped outwardly: Fig. 4 is a plan view of the needles holding loops showing the standing wale needles with loops stepped outwardly, with the newly added needle in position, also showing the newly kinked yarn, 20 with the two sinkers on either side of the added needle, not in action: Fig. 5 is a plan view of the needles with the loops formed from the yarn fed to them in the previous figure: Fig. 6 is a drawing of the fabric as it comes from the machine: Fig. 7 is an end view cross section on line (C—C) of Figs. 8 and 9: Fig. 7a is an enlarged sectional view of a detail of Fig. 7. Fig. 8 is the upper portion of the front elevation of the machine: Fig. 9 is the lower portion of the front elevation of the machine: Fig. 10 is a partial plan of the under side of Fig. 9: Fig. 11 is a front elevation of the body needle jack control stepping and raising devices taken on line a—a Fig. 7: Fig. 12 is the front elevation of the standing wale jack mechanisms, with the body needle bed removed: Fig. 13 is a plan view of the machine: Fig. 14 is a sectional plan view through line a—a Fig. 8 and line a—a Fig. 12: Fig. 15 is a plan cross section through line b—b Figs. 8 and 12: Fig. 16 is a plan section on line a—a Fig. 9, also being a plan view of Fig. 11 along line c—c Fig. 7: Fig. 17 is a plan cross section through line b—b Fig. 7 at the commencement of knit-

ting the tip of the toe. Fig. 18 is a front elevation of Fig. 17: Fig. 19 is a view similar to Fig. 17 but with the operating parts in position as they would be after having knitted the toe at line (d) Fig. 6: Fig. 20 is a front elevation of Fig. 19: Figs. 21 to 30 inclusive are diagrammatic plan views, showing the needles as they stand in relation to each other at various times while knitting the stocking blank shown in Fig. 6. In these views the needles shown by plain circles are those body wale needles upon which knitting is taking place, being always shown in the upper of the two lines of needles, such of these needles as have not been put in position to knit being shown by broken circles in the lower of the two lines of needles, it designates that such body wale needles are in a position to knit but are not knitting at the particular time. Those needles that form the standing wales or stepping needles are represented always in the upper of the two lines of needles, if in action are shown by black dots and if not in action are shown by broken circles. Fig. 21 shows the needles as they are while knitting the first course of the tip of the toe as shown along line (C) Fig. 6: Fig. 22 shows the position of the needles as the fabric has been widened as wide as the standing wale group will widen the toe, along line (D) Fig. 6: Fig. 23 shows the position of the needles as they are at the finish of the toe widening, along line (E) Fig. 6: Fig. 24 shows the position of the needles as they are at the finish of the foot widening, shown along line (F) Fig. 6: Fig. 25 shows the position of the needles while the outer groups are knitting the sole ravel following the knitting of the widened foot, while the instep needles are idle, their loops in their hooks, shown along line (F—x) and (x—F) Fig. 6: Fig. 26 shows the position of the needles while certain of them are making the setup of the heel flaps on alternate needles along line (G) Fig. 6: Fig. 27 shows the position of the needles along the same line as Fig. 26, but with all the setting up needles along line (G) Fig. 28 shows the position of the needles after widening out the heel flaps, shown at (G') Fig. 6, this needle arrangement being held throughout the knitting of the remainder of the heel flaps: Fig. 29 shows the position of the needles along line (J) or the first course to be knitted after heel flap knitting, including the instep needles, since the commencement of the heel flaps. This needle arrangement continues throughout the knitting of the narrow leg portion, as shown at (J') Fig. 6: Fig. 30 shows the position of the needles when knitting the last widened course of the leg along line (K) Fig. 6. This needle arrangement continues throughout the knitting of the leg unless a second widening at the top of the leg is desired, in which case the standing wale

needles in the (C) group would step out again as they did between the lines (J) and (K).

Figs. 31 to 40 inclusive are diagrammatic views showing the position of the different

- 5 needle groups at different times in the knitting of the stocking. These views are taken looking at the machine with intervening mechanisms removed, in the direction of the arrow XV, shown in Fig. 7, all these views
- 10 show in their upper portion, group lowering ledges and below these the upper butts of the body wale needle jacks and further down the lower butts of the body wale needle jacks, and further down the upper levelling
- 15 ledges for the control jacks under which are the control jack butts and under these are the controlling jack butt raising ledges. These views further showing diagrammatically the pins that operate the jacks for the stepping
- 20 needles, only such pins being shown as are holding butts in the path of the operating means, such butts being shown in lighter lines than the butts in action for the body wale needles.
- 25 The butts of the standing wale needle jacks are in these diagrammatic drawings shown in high or low positions, with the lower butt shown solid or dotted. If in a high position, and with lower butt solid, it designates that
- 30 the needle co-acting therewith is to be raised and form loops before the next stroke. If high and with its low butt dotted, it designates that the needle remains inactive with its loop in its hook. When down low, in
- 35 which case the low butt is always dotted, it designates that the needle co-acting therewith is drawn down in its retracted nonworking position and when so shown, the lower butt of such jack is always withdrawn in-
- 40 side the cylinder wall so that the needles co-acting therewith cannot be projected upwardly to permit the sinkers to feed yarn to them. The lower butts which are the controlling butts of the jacks 5 can be in two
- 45 positions, high and low. When high, it designates that needle jacks co-acting therewith are standing high but have their lower butts withdrawn into the needle bed, as, for instance, the instep needles while the heel flaps
- 50 are being knitted, so that they cannot be operated upon by the raising means but can still hold their loops. When these control butts are shown in their low positions in combination with needle jacks in their low
- 55 positions, it designates that the lower butts of such needle jacks are withdrawn inside the needle bed wall and that needles co-acting therewith have been retracted so as not to function. When such control jack butts are
- 60 shown low with the needle jack co-acting therewith shown high, it designates that the needles co-acting with such needle jacks are in the active position and will be raised to have yarn fed to them by the sinkers as such
- 65 needle jacks have their lower butts protrud-

ing outside the needle bed wall and can therefore be acted upon by the raising and lowering means.

In these diagrammatic drawings there are also shown circles representing the operating means for the stepping needles. In conjunction with these circles are shown the jack butts for operating these needles. Such of these butts that are shown will be operated to raise their needles on the next course. Fig. 70 31 shows the needle and jack control butts at the tip of the toe: Fig. 31a showing the position of the body wale needle jack in its high position ready to be operated by the raising means, the control jack butt being 75 shown in its lower position, the upper end of this jack holding the lower needle jack butt out beyond the edge of the needle bed: Fig. 31b shows the position of the body wale 80 needle jack in its low position with its lower butt withdrawn inside the needle bed with its control jack in its low position: Fig. 32 shows the needle and jack control butts at the end of the widened foot: Fig. 33 shows the needle and jack control butts after the 85 widened foot course previous to the ravel 90 courses and while knitting the ravel and during the foot cast off: Fig. 33a shows the position of the body wale needle jack in its high position with its lower butt withdrawn 95 inside the needle bed wall, being held in this withdrawn position by its control jack butt being in its high position: Fig. 34 shows the needle and jack control butts after the 100 widened foot has been cast off: Fig. 35 shows the 105 needle and jack control butts at the time of setting up the heel flaps: Fig. 36 shows the needle and jack control butts after the widened and continued heel flap courses: Fig. 37 shows the needle and jack control 110 butts previous to the first course after finishing the heel flaps: Fig. 38 shows the needle and jack control butts after the last widening course of the leg: Fig. 39 shows the needle and jack control butts after casting off 115 the leg, retaining only the loops which will form the tip of the toe: Fig. 40 shows the needle and jack control butts as in Fig. 39 except that all body wale needle jacks have been drawn down so as to become idle leaving only enough of them in action to knit the toe tip. The cycle of operation continues 120 back to Fig. 31.

In Figs. 41 to 68 inclusive are shown the movements of the left hand stepping needle 125 jack control pin cam, when viewed from the front. These figures are diagrammatic, it being imagined that all surrounding mechanism has been removed, with only the cam functions being shown. Such pins as held their jacks with their butts in the path of the needle raising means are shown in plain circles. Such pins as have permitted their jacks with their butts to withdraw from the path of the needle raising means are shown by black 130

dots. These figures are to be followed in conjunction with Figs. 21 to 40 inclusive.

In general, the machine shown in the above noted figures is constructed with a fixed vertically standing main needle bed bolted in position between two side frames, with needles therein, mounted to freely, in groups, slide up and down. In this needle bed are the body wale needles, such needles being capable of movement up and down with a supplementary movement causing these needles to retract their beard ends into the needle beds to permit another group of needles to form loops in their places. These needles are equipped at their lower ends with a swinging jack capable of withdrawing their butts inside the outer face of the needle bed, through the medium of a control jack which is mounted in the same slot. This part of the invention forms a part of a prior application of the present applicant for knitting machines, Serial No. 631,071, filed April 10, 1923, and now pending. These control jacks are equipped at their lower ends with a butt through the medium of which they can be raised and lowered singly, in groups or collectively as the design of the stocking warrants. The needles with their jacks are raised and drawn down en-masse. Such jacks as have their butts withdrawn so as not to protrude outside the needle cylinder are not raised, and those whose butts protrude are raised. Mounted in narrow needle beds in close relation to the above mentioned body wale needles are those needles that knit the standing wales and part of the toe. These are known as the stepping needles and their jacks. These groups of needles are capable of being stepped out with their loops while widening and capable of being caused to assume their original position quickly as the occasion requires, after having cast off their loops. These needles are caused to be raised and lowered by their jacks having a butt capable of being projected or retracted into and out of the path of the raising and lowering means which is the same raising and lowering means that function on the body wale needles. There being mechanism provided for stepping out these narrow needle beds and other mechanism for stepping the pattern control mechanism for projecting and retracting the jack butts and also to keep the pattern mechanism in time with the stepping out and in of these needle beds.

The needles are caused to be pressed by being flexed outwardly against a pressing surface formed on the noses of the walls which form part of the sinker and web holder bed. This bed is bolted in position between two side frames and is composed of a front sinker and web holder bed and a back sinker bed. Both the beds are slotted shallowly for the

purpose of locating removable walls, between which the sinkers and web holders slide.

The web holders and sinkers are separated by a flat bar running the full length of the machine. The sinkers are equipped at their needle end with a sinker head notched to receive yarn fed to it by any well known construction of yarn eye. The lower end of this head which is very much thinner than the body portion of the sinker is buried in a groove formed in the nib of the web holder. This portion of the invention forms a part of a prior application of the present applicant for knitting machines, Serial No. 71,316 filed November 25, 1925, Patent No. 1,786,255 and now pending. The sinker is further equipped with butts acted upon by jacks which are mounted below them. These jacks are operated by slur-cocks similar to Cotton systemed machines. Mounted above the sinker bed are the dividing sinker bars and withdraw bars.

The web holders are caused to operate en-masse, being equipped at their lower ends with butts operated upon by an oscillating bar which through links and levers is driven by some running part of the machine. This drive forms no part of the invention and is shown in the drawings in the form of a rotating shaft running the full length of the machine upon which are mounted cams and discs which cause this web holder lever or other levers to be raised and lowered, or can be of any suitable construction.

The stepping devices, of which there are three shown, one for bodily moving the stepping groups of needles, one controlling which of these stepping needles are to function to knit, and one for the stepping mechanisms for selecting which of the main or body wale needles are to function. The stepping outwardly is all mechanical through the aid of ratchets and racks which are prevented from moving outwardly beyond the required distance by tapes which operate around idlers and are weighted. These weights also function to cause these stepping devices to quickly assume at times their inner positions.

While only one section of the knitting machine is shown, it is not intended to limit the possible construction to any number. It will be quite obvious on an examination of the drawings that any number of sections can be used and while certain mechanisms are shown, it is to be understood that any number of mechanical movements are possible to use to accomplish the same results and it is not intended that the invention should be limited to the specific mechanism shown. Having now made a comparison between certain commonly used systems and the contemplated system, having explained the various views of the appended drawings, and having given a rough outline of the general

construction, I will now describe the detailed mechanisms that have been worked out in this application, in order to disclose to others the principles and aims of the invention.

- 5 This invention contemplates the production of wrought stocking blanks of the type shown in Fig. 6. For the sake of clarity and simplification in the making of the drawings, the gauge of the machine is shown in 10 the drawings as being quite coarse, the full width of the stocking using 89 needles, said needles being numbered when standing at the front of the machine commencing with needle #1 at the right hand side going to needle 15 #55 at the extreme left hand end. These 55 needles are the main body wale needles and are divided into three fixed groups containing 13 needles in the right hand group when viewed from the front, these needles 20 being numbered from 1 to 13 inclusive: a second or central group containing 29 needles being numbered from 14 to 42 inclusive: a third group on the left hand side containing 13 needles being numbered from 43 to 25 55 inclusive, all as shown in Fig. 21. The central group of these needles form that portion of the stocking marked (A) on line (C) Fig. 6, being gradually widened out to (A—A). The right and left end groups of 30 these body wale needles go into action one at a time until four needles of each of these end groups are in action at (A—A) along line (F) Fig. 6. The remaining nine needles of this right and left end group go into 35 action one at a time and form that portion of the fabric shown by (a') at line (K) Fig. 6.

These three groups of needles we will, in 40 the future, speak of as the body wale needles and carry the part #1 in all figures except fabric and needle layout figures where they are individually numbered. It will be understood, however, that the applicant is not limited to the use of the body wale or 45 stationary needles mounted in fixed beds since, for the purpose of the present invention, body wales and other supporting beds need be stationary only with relation to each other and to the step needles. As herein 50 closed, these needles are mounted in slots cut in the back side of the needle bed 2, in which slots their jack butts are capable of being moved in and out and up and down having three positions, an extreme low position at 55 which time their needle beard end is retracted into the needle slot as shown in Fig. 7. This retraction is caused by the inherent spring in their needle shanks. An intermediate position which constitutes their knockover position 60 while they are knitting, and a high position as shown in dotted lines, Fig. 7, in which position the sinkers can sink yarn around their shank. These needles are held into the slots at about their intermediate position by 65 a bar 3. This bar is capable of being re-

moved endwise for the purpose of removing any one of these needles in case of wear or breakage, but is normally fastened to the needle bed 2. The lower end of these needles butts 1 are formed in the shape of a hook 70 to which the jack 4 is swingingly connected. This jack has an upper butt marked 4a and a lower butt 4b, the upper butt at all times protruding beyond the outer edge of the needle bed wall, while the lower butt is capable 75 of being retracted inside the edge of the needle wall or to project or stand outside the edge of the needle bed wall.

These jacks 4 are operated to swing in and out through the action of a control jack 5. 80 This jack is fitted at its lower ends with butts 5a. Nine of these jacks forming a group in the center portion of the machine are equipped with short butts 5b as shown in Fig. 16, the remainder of this central group 85 of 29 needles being equipped with longer butts 5a as shown in Fig. 16. All these jacks are held into their slots by the needle projection and retracting plate 6, Fig. 7, the needle bed being held rigidly bolted between 90 the side frames 7 by the bolts 8.

The top of the needle bed 2 is fitted with three horizontally sliding pins 9 acting upon a presser bar 10 standing in back of the needles. These pins are acted upon by an 95 endwise moving presser cam bar 11, said bar being held in the needle bed by the plate 12, all needles in the needle bed being held at their upper end by the bar 13 which is removable endwise for the purpose of removing 100 worn or broken needles.

Mounted between the side frames 7 are the upper sinker beds 14 and 15 bolted to the side frames 7 by the bolts 16 and 17, having fastened to their under sides through the medium of the screws 18, the lower sinker beds 19 and 20. These upper and lower sinker beds are slotted to receive the sinker walls 21. The front end of these walls are made of thicker stock, shown at 21a Fig. 14, for the purpose of completely filling the space between the thinned sinker heads and forming thereby the beard pressing surface. Between these walls are slidably mounted the sinkers 22 all of which are provided at the end near the needle with the thinned head 22a which is provided with a yarn notch 22b, all being further provided with an upwardly projecting butt 22c and alternate sinkers with lower projecting butt 22d and all sinkers with a lower projecting butt 22e at their rear end. 115

Also mounted slidably between these walls are the web holders 23 which are separated from the sinkers by the plate 55, said plate fitting in a slot in the walls and running the full length of the machine. The end nearest the needles is provided with a nib and thinned throat and knock-over as in ordinary web holder constructions as used in circular 120 125 130

knitting machines, being further provided at their rear ends with a downwardly projecting butt 23a.

The sinker butt 22c is operated upon by the 5 sinker dividing bar 24 which is carried in the levers 25 which are swingingly carried in, and caused to be operated by levers 28 through the medium of the rod 29. This butt is further acted upon by the sinker with- 10 drawing bar 26 carried in the levers 27 which are fulcrumly carried in and caused to be operated by levers 30 through the medium of the rod 31. The levers 25, with the bar 24, are further operated upon to cause the 15 bar 24 to go into and out of butt 22c contact by the flattened shaft 32, mounted in bearings above and in the sinker bed 15, said shaft being given a partial rotation by any types of mechanism not herein shown, not forming 20 part of this invention.

Certain of the sinker butts 22e are at times caused to be acted upon by the withdrawing picker plates 33 of which there are four, two on each side of the machine center. These 25 plates are rigidly carried in the lever 34 swinging on pin 35 in the lever 36, said lever swinging on pin 37, being acted upon their lower ends by levers 39 which are fulcrumed on pins 39a carried in ears forming a part of 30 the cover 85 of the stepping needle pin control support. There being one lever 39 for the right hand levers 36 and one for the left hand levers 36. The levers 39 are equipped with rolls 38 which are acted upon to lift 35 said lever by the medium of the cams 98 of which there are two, one on each side of machine center line. Both being connected to operating bar 95, one lever being lifted and the other lever lowered as this bar goes to 40 the right or left in its movement of operating the stepping racking mechanisms. The pin 37 is carried in the support 40 to which is fastened the spring 41 operating to hold the lever 34 with its plate 33 out of butt contact. The two outer levers 34 are at times raised by bar 42, said bar being carried by 45 the levers 43 being caused to operate through the turning of the shaft 44. The two inner levers 34 are caused to at times go into butt contact through the action of the bar 45 carried by the levers 46, being caused to operate 50 through the turning of the shaft 47. Shafts 44 and 47 are turned through the agency of any type of pattern mechanism.

The sinker bed 20 is formed at its lower end into supports carrying the sinker slur- 55 cock slides being fitted with tapered gibs 43 and 48a upon which the sinker slur-cock cam slides 49 and 49a operate, sliding endwise thereon, carrying the sinker slur-cock cam 60 50 and 50a. The flat springs 51 and 51a friction these bars throughout their endwise movement, said spring being held in position by the cover plates 52 and 52a, endwise move- 65 ment being imparted to the bars 49 and 49a

by any type of reciprocating mechanism as is customary in machines of this type.

Swingingly mounted on the shaft 54, which is fixedly carried in the side frame 7, are the swinging jacks 53, their upper ends operating against the sinker butts 22d, there being one swinging jack for every two sinkers operating upon alternate sinkers that are equipped with the butt 22d. There are two types of swinging sinker jacks, one type 53 knitting the thin fabric forming the instep fabric (A—A) Fig. 6 of comparatively short loops and the other type 53a knitting the comparatively long loops of the sole and reinforced portions, all jacks being operated alike by the sinker slur-cock cam 50a at such time as like loops are desired. At such time the sinker cam slide 49a only is reciprocating, while at such times as in the foot and high splice when two types of loops are desired in 85 the same course, both sinker cam bars 49a and 49 reciprocate. The slide 49 carrying the sinker cam 50 which operates only upon the sinker jacks 53a causing them to operate a greater distance for the purpose of causing 90 the sinkers to sink more yarn. The different adjustments necessary for the sinker bars 49 and 49a are given through the medium of the manually, although same can be automatically controlled, adjustable gibs 48 and 48a. 95

The web holder butts 23a are operated to force the web holders inwardly and to withdraw them by the in and out reciprocating bar 56 which causes the web holders to perform like functions, although it might prove desirable to have this bar in sections, forcing certain of the web holders further forward, in conformity with the varying sinker stroke, while knitting two lengthened loops. This bar 56 is carried by the levers 57 of which 100 there are three, said levers being rigidly connected to the rotarily reciprocating shaft 58 which is carried, in bearings in the side frame 7. This shaft 58 is caused to move through the medium of the lever 59 fastened thereto, being connected through the medium of the pin 60 to the link 61 which is connected to the lever 62 through the medium of the pin 63. This lever 62 fulcrums on shaft 64, said shaft being journaled in bearings carried in the side frame 7, the other end of the lever 62 being fitted with a roller 65 operating upon cams carried on the drive shaft 66 or in any other well known manner. 110

The machine is further fitted with groups 120 of needles which we will call stepping needles of which there are four groups, containing 34 needles, these needles carrying the group part #70 in all figures except fabric and needle layout figures, where they are individually numbered, there being two groups on each side of the machine center. The outermost right hand group, when viewed from the front of the machine, containing four needles, numbered from 1 to 4 inclusive. 125

The group near the center on the right hand side is composed of 13 needles, numbered 5 to 17 inclusive, while the group near the center on the left hand side is composed of 13 needles, numbered from 18 to 30 inclusive, and the outermost left hand group composed of four needles is numbered from 31 to 34 inclusive, as shown in Fig. 21. These needles, each in their group, are guided to hold their proper gauge by the comb 67 of which there are four, one for each group. These combs are rigidly mounted on the stepping needle beds 74 and at their upper ends are further supported by the contact with a groove formed in the upper portion of the needle bed 2.

They are caused to move endwise by the comb like plates 68, of which there is one for each group. In order that, as these groups of needles are moving endwise, they do not interfere with the retracted needles 1, the stand carrying them is equipped with the iron 69, of which there are four, one for each group. This iron has a slot cut through it to permit its group of #70 needles to freely move up and down. The iron acts to make certain that the inactive retracted body wale needles 1 underlying any certain group of stepping needles are with certainty positioned in the bottoms of their slots, even though their spring like tendency is for any reason impaired. These irons 69 and the comb like plates 68 are carried in the stands 71, of which there are four, one for each group. Said stands carry their respective short needle beds 72 rigidly fastened thereto. On the sides of these stepping groups which will later, when two groups come together, be in close relationship, these needle beds 72 are supported by thin plates 73, so as not to interfere with getting the needles 4 and 5 and 30 and 31 in proper gauge.

The stands 71 are rigidly fastened to the upper surface of the short jack beds 74 of which there are four, one for each group of these needles. These beds are mounted for endwise movement in the support 75 which is rigidly fastened between the two end frames 7 through the medium of the bolt 76. These beds are slotted to receive the swinging jacks 77 which are connected to the needles 70 through the medium of the connecting jack 78. These needle beds 74 are held in their innermost position toward the machine center line by steel tapes 79 operating around idlers 80, said idlers being capable of free rotation on the studs 81, the tapes 79 being further idled around idlers 82, being mounted for free rotation on the shaft 83 which is the full length of the machine and rigidly carried in the side frames 7. The lower depending ends of these tapes are equipped with suitable weights causing the needle beds 74 to at times be caused to stop against their stop pins 84, which are fastened in the bed

support 75. The studs 81 are fastened in the bed cover 85 which is rigidly fastened to the support 75 through the medium of screws and bushings 86. The upper and outer ends of the bed 74 having rigidly fastened thereto short sections of ratchet racks 87, one such ratchet rack being fastened to each bed 74. Mounted between the cover 85 and the support 75 are the pawls 88 and 89 being normally held in rack contact by their springs 90. The pawl 89 being mounted to swivel on the pin 91 which is rigidly fastened in the cover 85, its outermost end being under control of the bar 92 which is formed with the cam surface 92a, which upon endwise movement of the bar 92 can cause it to be withdrawn from rack tooth 87 contact. The bar 92 can be controlled by any well known type of pattern mechanism. The pawl 88 is caused to rack the ratchet racks 87 through the medium of the gears 93 fitted with eccentrically located pin 94, which upon rotation of the gears causes the pawl 88 to step the ratchet rack 87, one tooth outwardly away from the center of the machine and through this action imparting to the beds 74 with their stands 71 and their short needle beds 72 carrying the iron 69 and the comb plate 68 endwise stepping movement with their needles therein. The pawl 89 prevents the falling back toward the center of the group by locking said group in the position to which the eccentric operated pawl 88 pushed them. The gear 93 is caused to reciprocatorily rotate through the medium of the bar 95. This bar in the present construction is continually reciprocating with the proper timing by any well known construction of reciprocating mechanism. Pattern devices acting on the bar 96 which has a cam like surface 96a formed upon it acting upon the outer end of the pawl 88, control said pawl as to whether it will step out its group or not. In order to step out its group, the bar 96 must be through pattern control placed in such position that its portion 96a comes opposite the end of the pawl 88, such pattern movement taking place just previous to the reciprocation of the bar 95. After the pawl 88 racks a sufficient number of teeth with the pawl 89 locking it against the pull of the tapes and counterweights, and it is then desired to hold the group in a given position, the bar 96 takes out of tooth contact the pawl 88 so that although the pawl 88 continues to be operated by the eccentric through the continued movement of the bar 95 and gear 93, it will no longer step out this group of needles. If it is now desired to cause the group of needles to fall in to its inner most position to the center of the machine, the pawl 89 is caused to be taken out of tooth contact through the action of the cam surface 92a formed on the bar 92, thereby permitting the counterweights through the action of the tape which is con-

nected to the stand 71 through the medium of the hook 97 to quickly act.

Similar action takes place at either or all of the four groups, each group having its stand 71, with its parts and the needle bed 74 with the ratchet racks 87 and the pawls 88 and 89 with its eccentric pin 94 and gear 93, all of them being operated by the one bar 95. This bar received its movement at each end of the machine traverse. The control means 96 a and 92 a formed in the bars 92 and 96 are so arranged that they can either take out of action all four pawls or the pawls of two groups on either side of the machine center so that the stepping out process can never take place at both ends of the machine at once, by preference taking place on the side of the machine farthest away from the yarn eye, that is, the widening needle is, by preference, inserted at the end of a group farthest away from the yarn eye. With this mode of operation the yarn is fed to the newly added needle in the customary manner so that upon the return stroke of the yarn eye the yarn is securely held in the needle hook to insure the proper formation of the selvage edge, whereas if the needle is added to the near side, some means must be found to insure that the yarn is properly fed to the new needle on the return stroke of the yarn eye.

Integrally connected and fastened to the upper side of each one of the narrow jack cylinder needle beds 74 are the supports 40, each support carrying its fulcrum pin 37, upon which the right hand levers 36 operate through the levers 39 at every movement of the control bar 95 to the left, the left hand levers operating when the bar works to the right through the medium of the cam 98 fastened thereto. There being a cam 98 for each lever 39, the raising angles of the cam on the right hand side of the machine operating to raise their lever when the bar 95 through its movement operates the pawls 88 to come into ratchet rack 87 contact. While the right hand lever 39 is operated by its cam 98, the lever 39 on the left hand side of the machine drops off its cams 98. The right hand and left hand levers therefore moving alternately. Through the movement of the levers 39 riding up the cam angles formed on the cams 98, movement is imparted to the levers 36 and through them movement outwardly to the levers 34. Unless the levers 34 are raised into butt 22 e contact, levers 36 and 39 move without effect upon the fabric, but when the levers 34 move outwardly having first been put into butt 22 e range by the raising of their bars 42 or 45, the plate 33 co-acting with whichever lever 34 has been raised acts to draw two sinkers into their extreme outermost positions, as shown in Fig. 7, thereby preventing these two sinkers from being acted upon by the sinker jacks 53 or 53 a . The position of the two sinkers

not operated upon to sink yarn, as explained above, is such as to prevent yarn from being kinked around the widening needle for its first course. The position of the upwardly extending nose of the plate 33 in relation to the needles of the stepping group of which it forms a part is such that it will always withdraw the sinker next to the last needle forming its group toward the center of the machine and the sinker beyond toward the center of the machine always maintaining this relationship toward this end needle. Sinkers only being withdrawn at such times as the new widening needle is inserted and then only during the first yarn feeding course. A new widening needle is never added at both ends of the machine at once and should always take place on that end of the machine farthest away from the feeding eye.

As there comes a time when it is necessary that the right and left hand outer groups of stepping needles be moved to their most outward position from a more inner position suddenly and not tooth by tooth, all the stands 71 have a hole cut through them, as shown in Fig. 7, through which two rods 99 and 100 slidingly operate. The rod 99 is provided with a pin 101 which upon endwise movement of the rod will take along with it the outer right hand stand 71 and with it all parts integrally fastened thereto including its group of needles. After such endwise movement of the rod 99 and the subsequent locking of the stand in its most outward position, by its locking pawl 89, the rod 99 falls back to its normal position in order to permit the stand 71 to fall back to its more inner position upon the operation of the bar 92 to release the pawl 89. The movement toward the center of the machine of the stands 71 being caused by the action of their weighted tapes acting through the idlers 80 and 82. The rod 100 being similarly operated and equipped with pin 102 but operating on the left hand stand 71 to cause it to operate in a similar manner as explained for the right hand side.

The lower portion of the jacks 77 carried in the beds 74 are equipped with a butt 77 a upon which the action of raising and lowering their needles takes place. These jacks 77 are capable through swinging on their pivoted connections on their jacks 78 of withdrawing their butts to within the bed wall in which position they will not be acted upon by the raising and lowering plate 6. Each jack being acted upon by its spring 77 b to cause it to assume its retracted butt position at such times as it is desired to cause its needle to become inactive. In the lower end of the beds 74 and underlying the lower end of the jacks 77 are the pins 103, there being one pin for every jack, their position in the bed being staggered. The two stepping

groups of beds on the left hand side of the machine when viewed from the front having their pins in a somewhat higher position than the two right hand stepping groups of beds, in order that the pattern cams acting upon the left hand groups will not effect the right hand groups, and vice versa. Mounted back of the beds 74 and pivotally carried on a shaft 104, said shaft being mounted for free turning movement in bearings carried by the side frame 7, are the two levers 105, same being pinned to the shaft 104 and both levers terminating toward the front of the machine in the base like ends to which are rigidly fastened the stepping groups bar supporting pieces 106 and 107. These pieces being formed into one piece through the medium of the bushings 108 rigidly secured together by the screws 109 forming between them guides for the operating bars 110 and 117 and the pattern control bars 111 to 116 inclusive, and also guides for the pin control slides 118 and 119 to which are fastened the ratchet racks 120 and 121. These bar supporting pieces 106 and 107 further support between them the racking pawls 121 to 126 inclusive. Driven through these bar supporting pieces 106 and 107 is the locking pawl pin 127 upon which the lock pawls 123 and 124 pivot.

This assembly of parts carried by the pieces 106 and 107 being capable of being raised and lowered at its pin 103 end by the slight rotating of the levers 105 and the shaft 104 through the action of the cam 200 carried on endwise shiftable bar 201, said bar being slidably carried in the support 75 and being under the control of any suitable pattern mechanism. The cam 200 forming by its surface 200a, Fig. 12, a support for the assembly 106 and 107 through the medium of the pin 202, said pin being a part of a bracket 203 fastened to the upper side of the piece 106.

As it is at times necessary to raise the assembly into two other positions to that shown in Figs. 7 and 12, this cam 200 has two lifts or angles forming rest 200b and 200c. The time in the production when it is necessary to raise the assembly 106 and 107 with its slides 118 and 119, carrying the pin cams 133, is as shown in the diagrammatic layout of this cam shown in Figs. 41 to 68 inclusive, cam 200 resting on surface 200a up to and including Fig. 58, being raised and resting on surface 200b in Fig. 59 and so resting up to and including Fig. 61, being further raised and resting on surface 200c in Fig. 62, being lowered again to surface 200b in Fig. 63, resting on this surface up to Fig. 65 inclusive, being lowered to surface 200a in Fig. 66 and so remaining through out the remainder of the cycle.

The pin control slides 118 and 119 being held in their inner retracted position through

the medium of the tapes 128 connected to the slides by pins 129, these tapes operating around idler rollers 130 and 131, said tapes being fitted with counterweights which always tend to cause the slides 118 and 119 to be drawn inwardly against their pins 132, unless prevented from doing so by the locking pawls 123 and 124. Fastened to the slides 118 and 119 are the pin cams 133 fitted with an angle 133a at one end and the angle 133b and 133c at their lower edges, the angle 133a forcing the pins 103 with which it comes in contact toward the front of the machine overcoming the tendency of the spring 77b and thereby placing butt 77a of the jack 77 with which the acted upon pin 103 is associated, in bar 6 contact, thereby causing the needle associated with said jack 77 to be raised at the next subsequent lift of the bar 6.

The slides 118 and 119 are racked outwardly, 118 by pawls 121 and 122 and slide 119 by pawls 125 and 126, the first two pawls being operated by the eccentrics 134a and 134b, a part of the gear 134, the other two pawls operating the slide 119 are operated by the eccentric 135a and 135b, these eccentrics forming part of the gear 135, as shown in Figs. 17 to 20 inclusive, the gear 134 being caused to reciprocate by the endwise movement of the operating slide 110 and the gear 135 being caused to reciprocate by an endwise movement of the operating slide 117. The slides 118 and 119 as they are stepped outwardly only adding one pin at a time to the active group by their cam surfaces 133a. These cam surfaces never both move together at the end of any one stroke of the machine, but act alternately always at that side of the machine farthest removed from the yarn eye. As long as the beds 74 are not in themselves stepped outwardly, the cams 133 can bring a new pin into action by being moved outwardly the amount equal to the distance between pins, but when the beds 74 are at the same time stepped outwardly the distance of one needle center, in order to add another pin to the active group, it becomes necessary for these slides 118 and 119 to be moved outwardly twice the distance of center to center of pins. For this reason the ratchet racks 120 and 121 have teeth of two lengths, one for racking a double space which functions during the time the beds 74 are being racked, the other length being for single spaces, which functions at such times as it is necessary to make new pins active while the beds 74 are not stepping outwardly. The bar supporting pieces 106 and 107 have further fastened to them the pin pieces 136. These pieces are not stepped outwardly but remain fixed endwise, their purpose being to permit the pins carried in the outer stepping groups, if they are acted upon by cams 133a, to hold these pins in the position that the cam 133 put them, as the outer stepping bed 74 is

further stepped outwardly. The operating slides 110 and 117 being continually reciprocated by any well known type of reciprocating mechanisms, their stroke being of sufficient length to rotate the gears co-acting therewith a half turn, thereby causing the eccentrics forming part of the gears to operate the pawls co-acting therewith. The pawl 121 acts on the eccentric 134a a distance equal to pin centers and the pawl 122 acts on eccentrics 134b a distance of two centers, and the pawl 126 acts on eccentrics 135a a distance of one center. The sliding action of the two bars 110 and 117 being oppositely arranged causing the pawls operating on the slide 119 to act at one end of the stroke, and causing the pawls acting on slide 118 to operate at the opposite end of the stroke, each slide being operated while the yarn eye is 20 the farthest away from its end.

In order that the above mentioned pawls are not continually working in the ratchet bar teeth, their outer ends are controlled by control bars, the pawl 121 being controlled by the bar 111, pawl 122 by bar 112, pawl 125 by bar 115 and pawl 126 by bar 116. In order that if and when the pawls rack the slides 118 and 119 outwardly, said slides will not be returned to their more inner position 30 through the action of the tapes and weights, the lock pawls 123 and 124 lock the slides in any position to which they were put by the racking ratchet pawls. These locking pawls function at all times, with the exception of 35 such times as the slides 118 and 119 are to fall inwardly toward the center of the machine as for instance at the finish of one stocking and before the commencement of the other. At such times, the outer ends of 40 these locking pawls are operated upon by their control bars 113 and 114; 113 operating on the pawl 123, and 114 on the pawl 124. These pawls pivot on the pin 127. All pawls 45 are caused to go into ratchet rack contact through the action of their spring 137, unless prevented from doing so by their control bars.

The needle projecting and retracting plate 6 is equipped at its upper end with butt 50 grooves running the full length of the machine; a butt groove 6a toward the front of the machine, and a butt groove 6b toward the back of the machine. The front groove acts upon the body wale needle jack butts 4b, 55 and the back groove acting upon the butts 77a of the stepping needles, in both cases, of course, only when the butts of these elements are projected beyond their beds. This plate is equipped at either end with bearings 138 60 which are rigidly fastened thereto. These bearings have pinned to them the rods 139. These rods are guided in holes in the needle bed 2, the bearings projecting toward the back of the bed through openings. The plate 6 reciprocates up and down causing the jacks

with their needles to be raised so that their beards are above the yarn sinking line and retracted so that their hooks assume the proper position at about the knock over line of the web holders. The plate 6 has rigidly fastened to its lower end a pin 140 about centrally disposed, this pin carrying to freely rotate the roller 141. This roller works in a cam groove formed in the cam bar 142, said bar being slidingly supported for endwise movement in the side frames 7. The endwise reciprocatory movement being given this cam bar through the action of a sector 143, this sector being caused to reciprocate turning on shaft 64, upon which shaft it is prevented from endwise movement by the collars 144. Reciprocation is imparted to the sector through cams carried on shaft 66 or through any other well known reciprocating devices. The end of the sector is equipped with spiral 80 cut teeth, as shown in Fig. 12, acting in angularly cut teeth in the bar 142.

The body wale needles 1 are capable of assuming three positions, an extreme low position, at which time their beards are fully retracted in the needle bed 2; another position, at which time their hooks are in proper relation to the web holder knock over surface as when knitting; a raised position as shown in dotted lines in Fig. 7, in which position the sinkers can sink yarn around their shanks below the tip of the beard as in normal practice. When #1 needles are in their knock-over position, their jacks 4 either have their butts 4b protruding outside the needle bed wall, as shown in Fig. 31a or have their butts 4b withdrawn inside the needle bed, as shown in Fig. 33a. In the first mentioned position, these jacks would be acted upon to raise their needles at the next upward movement of the plate 6. In the second mentioned position, the plate 6, at its next upward movement could not raise such jacks and needles, thereby permitting them to remain with their hooks at about the knock-over, as shown in Fig. 7. In order that #1 needles remain in their extreme low position, it is necessary that their butt 4b remain retracted inside the needle bed, as shown in Fig. 31b. In order to cause such extremely low positioned needle to become active, it is necessary that the jack 5, co-operating therewith be raised from the position shown in solid lines, Fig. 7, to the position shown in dotted lines in this figure and shown in solid lines in Fig. 33a. This upward movement of the jack 5 raises the jack 4 co-operating therewith to the position shown in 33a. This would cause the needle connected with this jack to be forced outwardly by its hook end acting upon the bevel formed in the under side of the bar 10, as shown in Fig. 7a. Continued upward movement raising this needle so that its hook end would be about at the knock-over position, 110 the wall 1b formed in the upper end of the 115 120 125 130

needle bed 1 guiding the needles when in this position. These walls 1b being so shallow that while they will give side support to any needle held between them, whether it be body wale or stepping needle, it will permit of the stepping needles snapping by as they are stepped outwardly or inwardly.

This upward movement from the extreme low position to the knockover position must never take place while the iron 69 is in contact with the needles.

10 Needles being only so raised as to fill in the space made by the stepping out of the stepping needles. As it is necessary at times to lower collectively a group of body wale needles from a position with their hooks at the knock-over at which time their jacks 4 are in a position as shown in 31a to a position as shown in 31b, in order to make certain body wale needles inactive with their beards retracted, it is necessary to 15 collectively raise the control jacks 5 operating with such needles, such raising being shown in Fig. 33a, before the needles 1 can be lowered with their jacks at a position shown in 31b, in order that their beards will 20 be in the extreme low position retracted. This group upward movement is given the control jacks by their butt lifting plates, there being four of these plates, two on the 25 right hand side of the machine and two on the left hand side of the machine, which we will call inner right hand plate 156, outer right hand plate 157, inner left hand plate 158, outer left hand plate 159. These plates are 30 mounted on vertically slidable hollow shafts in the needle bed 2, numbered the same number as their corresponding plate, but marked (a), being held in their downward position by springs 160, the shafts being further 35 equipped at their lower end with forwardly projecting pins marked with the same number as their corresponding shafts but with the letter (b). The pins on the right hand side are acted upon by a cam 161 forming part 40 of a control bar 162. The pins on the left hand side are acted upon by a cam 163 forming part of a control bar 164. These bars are 45 endwise slidably supported in a lower projecting member of the needle bed 2, being held in their guides by the screw 165, being 50 operated endwise by any type of pattern mechanism.

The machine is further equipped with suitable short bars for lowering the jacks 4 after the control bars 5 have retracted their butts, as shown in Fig. 33a. This action taking place on the upper butts 4a and placing the jacks 4 and 5 in a position as shown in 31b. For this purpose, the machine is equipped 55 with four short bars, two on the right hand side of the machine and two on the left hand side, which we will designate right hand inner bar 145, right hand outer bar 146, left hand inner bar 147, left hand outer bar 148, 60 viewing them from the front of the machine.

These bars are rigidly fastened with screw pins 149 to vertical rods carrying the same number as the bars but lettered (a) carried in bearings formed in the needle bed 1.

These bars are normally held in their upper position by springs 150. They are equipped at their lower ends with collars of the same number as the bar but lettered (b).

The collars are equipped with pins protruding toward the front of the machine. The pins in the collars 145b and 147b are somewhat longer than the pins in collars 146b and 148b.

The left hand pins are acted upon by the cam 151 forming part of bar 152, the right hand pins being acted upon by cam 153 forming part of bar 154.

These bars are operated endwise by any suitable pattern mechanism and are guided by a bearing formed in the lower portion of the cylinder 1 and held in position by the screws 155.

The cams 151 and 153 are formed with two surfaces (a) and (b), (a) operating only upon the long pin and (b) operating on either long or short pin.

As it is desirable that when the plates 156, 157, 158 and 159 are rased as heretofore de-

scribed, and then lowered in conjunction with the lowering of the plate or plates 145, 146, 147 and 148 that there be a central group of body wale needles that are not lowered to the extreme low beard retracted position, the

plates 145 and 147 and plates 156 and 158 do not come in contact with this central group leaving this center group of needles uncontrolled.

This uncontrolled group of needles in the preferred method of knitting the stocking, by preference, never assume the extremely low position, as they are knitting or holding loops continuously, but it is necessary that this center group of body wale needles be

capable of standing idle with their hook ends at about the knock over position, holding their loops in conjunction with needles on either side of them throughout the knitting of the foot ravel and heel flaps.

It is necessary, therefore, at this period in the production of the stocking, insomuch as the jacks for this center group of needles are not controlled as a group as are the remainder of the needles by the plates 145, 146, 147, 148, 156, 157, 158 and 159, that suitable means be pro-

vided for causing their 4b jack butts which when active were as shown in Fig. 31a to be retracted out of contact with the groove in

plate 6, as shown in Fig. 33a.

This mechanism takes the form of a plate 166 having the groove 166a capable of raising and lowering the control jacks 5a underlying the center group of needles. This plate 166 is rigidly connected to the end of a vertically

sliding rod 167, said rod being slidably mounted for up and down movement in the needle bed 2, having pinned to its upper end the collar 168.

This collar is provided with a forward protruding pin 169 which is acted upon by the groove 170a formed in the end-

wise slidable bar 170. This bar has a seat formed for it in the needle bed 2 held in position by the cover 171 connected with the bed by screws, pockets being cut out of the needle bed 2 to permit of the movement of the collar 168, as shown in Fig. 15. The pattern mechanism necessary to slide this bar can be of any suitable type and is not here shown as it forms no part of the invention. When it is desired to idle this center group of needles and with their hooks at the knock-over permitting them to retain their loops, the bar 170 is moved endwise to the left raising the butts carried in the plate 166. When it is desired to again make these needles function, the bar 170 is moved to the right lowering the plate 166 with the butts of the control jack 5a.

As it is necessary that at times, as when widening the toe, foot and leg, when the stepping needles 70 in their stepping out form a space between the last body wale needle and the first stepping out needle, that body wale needles that are in extreme low retracted beard position, as shown in Fig. 7, be made active one at a time for the purpose of filling the space, therefore widening the fabric, mechanism is provided for so doing. Such extreme low and active needles with their jacks are in a position with their butts 4b retracted and with their control jack 5 butts in their low positions, as shown in Fig. 31b.

This mechanism takes the form of what I will call picking devices, said devices at the commencement of the stocking resting idle to the inside toward the center from the first to be added body wale widening needle, as shown in Fig. 16, in which figure the inner of the two picking devices have already moved outwardly one space ready to add the first needle on either side of the toe. These picking devices are in the form of narrow members capable of assuming a position over and under a butt of the control jacks 5. They form a part of and are connected to stepping out ratchet racked toothed members 171, of which there are four, an inner right hand member, an outer right hand member, an inner left hand member and an outlet left hand member. These pieces are slidably for endwise movement, mounted in the carrier 172, being held from rising by the cover 173, being normally held in their innermost position through the action of the tapes 174 idled around the rollers 175, said rollers rotating freely on studs 176 fastened to the cover 173 and forming part of the unit 172. Tapes then go to the back of the machine idled around the rollers 177, said rollers freely rotating on the rod 177a, their lower ends being weighted for the purpose of causing the pieces 171 to return inwardly against their stop pins 178. These racking pieces 171 are racked by pawls 179 operated by eccentric pins 180 forming part of the gear 181, said gear being operated a half turn by the continually reciprocating

bar 182, said bar being driven by any suitable reciprocating mechanism. In order that the racking pawl 179 does not at all times pick the pieces 171 outwardly, they are controlled by their control slide 183 acting upon their outer ends.

In order that when these racking pawls rack out the pieces 171 and that the pieces will be locked in the new position given them by the pawls, there are provided locking pawls 184 working in the ratchet teeth formed in the pieces 171, these pawls fulcruming on pins 184a fastened in the cover 173. The outer ends of these pawls are controlled by pattern bar 184b in order that when it is necessary that the pieces 171 be returned to their inner position that the pawl 184 can be raised out of ratchet rack tooth contact. All pawls are held, unless under the control of their bars, in tooth contact, through the medium of their springs 185.

In order that when the picking devices are brought in position over and under a new butt that said devices can raise the butt from its low to its high position, this entire picking unit 172 is raised bodily upwardly through the medium of two levers 186, securely fastened to the piece 172, the levers being rigidly secured to the shaft 187 which is journaled in bearings in the side frame 7. This shaft is slightly rotated by the action of the lever 188, provided with a suitable roller 189 operating on cams caused to be moved by the shaft 66 or with any other suitable driver or pattern mechanism. This driver or pattern mechanism forms no part of the present invention.

Upon this bodily upward movement such butt that is overlying the finger 190 will be raised, thereby raising the control jack 5, as shown in Fig. 33a, thereby having raised a needle whose beard was in the retracted extremely low position to a position with its hook at about the knock-over, but with its jack butt 4b still retracted inside the needle bed. On the subsequent going down of the picking unit, the top picking member 192 which forms part of the stepping out pieces 171, takes the butt of the control jack 5 down, thereby causing jack 4 to assume a position as shown in Fig. 31a and the control jack in a position also as shown in this figure. The member 190 is constructed to pivot on its pin 191 carried in the bearings 193 and held in 5a butt contact by the spring 191a for purposes not disclosed in this invention, such construction not being herein claimed. For the purpose of this invention, this finger could be a solid projection carried by the stepping out piece 171.

The control slide 183 has cams formed upon its inner surface which operate upon the ends of the pawls 179 so that either both right hand or both left hand or only outermost or only innermost pawls 179 can be

made active or inactive or all of them can be made inactive in order to produce the stocking desired.

One of a type of stocking that can be 5 knitted upon this machine is the stocking blank shown in Fig. 6 which is a stocking blank of a very similar type to that now produced on the footer and legger of the present day Cotton systemed stocking, only 10 in this machine the complete stocking is made automatically on this one machine here described. The stockings are preferably made one attached to the other. The group of loops in the position (A&B) along the line 15 (C) at the tip of the toe being the continuing loops from the top of the leg of the previous stocking. The needles forming the loops (A) are body wale needles and are the needles previously spoken of as the central 20 group of body wale needles. The needles forming the group (B) on either side of this central group of needles along line (C) are formed by the innermost needles of the right and left inner groups of the stepping out 25 needles. These needles preferably set up their loops along line (C) on alternate needles.

As knitting continues the stepping out needles step out one needle at a time taking 30 with them the loops which they hold in their hooks. This stepping out taking place on the side farthest away from the yarn eye. All stepping out and adding of needles takes place at the ends of the stroke. On whichever side this stepping out took place a body wale needle is inserted between the last body wale needle and the first stepping needle. At the time stepping out is taking place during knitting, widening takes place by 35 bringing in a new outer needle in the stepping groups, to widen the fabric at its edge, being always added while the yarn eye is at the opposite end of the stroke.

This continues on alternate sides with any 40 number of like width courses between until a line is reached along line (D) after which no more body wale needles are inserted, as the stepping needles do not step out after the line (D) during toe knitting. Stepping 45 needles, however, continue to be added on alternate sides at the outer ends of the stepping needle groups, until the line (E) has been reached, at which line the inner stepping needle groups have been stepped out to 50 their maximum distance. After which, like lengthened courses are knitted, until a point is reached previous to the foot widening as shown at (E'), after which the outer stepping needles are stepped outwardly in the 55 same manner as described for the inner stepping needles, body wale needles being inserted as heretofore described for the toe. After 60 which a group of needles comprising the instep portion of the stocking are idled, but 65 retain their loops while a ravel portion is

knitted on the sole needles along line (F), after which the needles that knit this ravel cast off their loops, while the instep needles retain their loops.

The outer stepping needles then fall into 70 their inner position which is the position they were in previous to the foot widening, after which those inner stepping needles that do not form a part of the idling instep needles and all of the outer stepping needles on both sides 75 of the fabric set up new loops preferably on alternate needles forming the lower end of the heel flaps as shown by line (G) Fig. 6. The outer stepping needles step outwardly, 80 new body wale needles being added as heretofore described in the toe and foot until a suitable width as shown by (G') has been reached after which the remainder of the heel flap is 85 knitted from line (G') to the line (H), where it is desired to continue knitting across the stocking forming the ankle. The fabric from (X) to (Y), being of such length, that when it is later in subsequent operations looped with the loops forming the widened sole fabric, it will contain as many loops as this latter 90 fabric.

Knitting then continues across the width 95 of the fabric shown by line (J), including the instep needles, until a point is reached in the stocking shown by line (J') Fig. 6, at which time the outer stepping needles are stepped outwardly, body wale needles being 100 inserted as described in the previous widening of the foot, until the desired width has been reached as shown by line (K). Further 105 top leg widening taking place if found desirable.

The fabric is later looped as previously 110 described with the selvage edge loops of (XY) joined to the loops of (XY') Figs. 1 and 6, as in present full fashioned stockings, the ravel knitted at (XY') being formed to facilitate this operation. The course of loops along line (G) forming the lower end of the heel flaps on each side of the stocking are then 115 looped together as in present full fashioned stockings, if desirable a ravel having been knitted along this line, if found desirable to facilitate this looping operation. The stocking blank is then sewed together along line (S) Fig. 1, as in present full fashioned practice, the welt being sewed or otherwise turned, this feature not forming part of this invention. After which the toe is looped, all loops 120 on the left hand side along line (C) of the group of loops (B) being joined to the left hand portion of the loops (A) while the loops on the righthand side along line (C) of the group of loops (B) are joined to the right 125 end portion of the loops (A), thereby effectively closing the tip of the toe as in present full fashioned practice.

It is planned to feed yarn in this machine in a somewhat similar manner to yarn fed in present full fashioned machines, the thicker 130

fabric toe, split foot, heel and high splice being formed in a somewhat similar manner, the mechanisms for so doing not forming any part of this invention.

Having now described and explained somewhat the type of fabric to be knitted and the mechanisms to be employed therefor, I will now describe in detail how the various parts function and are co-ordinated to perform their ends.

I will first point out that the yarn eye, as in ordinary full fashioned machines, traverses somewhat in advance of the wave formed in the jack sinkers. This wave is put into the sinkers through the action of the sinker jacks 53 and 53a operating on the butts 22d. The jacks are caused to move through the action of the cams 50 or 50a moving through the agency of the traversing bar 49 or 49a or both.

When these jacks are operated by only the traversing bar 49a with its cam 50a, all the sinkers kink the same amount of yarn, whereas if both sinker cams 50 and 50a with their traversing bars operate on the jacks, those

jacks that are formed as shown by 53a are operated upon by cam 50, thereby kinking more yarn than the jacks 53, for the purpose of feeding more yarn in certain courses to some of the needles, while the remaining needles receive less yarn from the sinkers operated by jacks 53 and cam 50a, as, for instance, those needles that knit the split sole and high splice require longer loops than those forming the foot, top and instep. Split

work is effected on the present machine in accordance with the usual practice in the manufacture of full-fashioned goods by yarn feed control although with the arrangement herein disclosed utilizing independent needles, this result could readily be obtained if desired by needle division. As the sinkers are cammed in, previous to which the needles that are to take yarn are raised, with the tips of their beards above the notch 22b

formed in the head of the sinker 22a, this sinking in full fashioned machines of present day design taking place in fine gauge machines on alternate needles only, so in this new practice, necessitating therefore that the amount of yarn kink by the jack sinkers must be of sufficient length to form two loops after the sinker cam traversing stroke is finished.

After this sinking traverse, the dividing bar 24 is dropped down into butt 22c contact through the rotation of the flattened shaft 32, after which this bar, through the medium of its lever 25 and the operating lever 28, moves forward, causing the sinkers not operated by the jacks to go forward, forming kinks around needles not having yarn kinked around them by the jack sinkers. The jack sinkers being pushed backward by the yarn as in present practice. The dividing bar 24

evens up the position of all the sinkers as is customary. The needles that were raised are

now drawn down by the plate 6 acting with its grooves on their butts through the medium of the roller 141 being acted upon by the incline 140a Fig. 8 formed in the groove in the bar 142, said bar moving endwise at the completion of the dividing sinker stroke, until the tips of the needle beards are about on line with the top of the nib of the web holders. The bar 142 resting with the roller on the level portion of the groove 140b Fig. 8 at which time the presser bar 11 is caused to move to the left Fig. 14, thereby acting with its angles 11a on the pins 9 forcing the presser plate 10 outward, thereby causing the needle to be flexed toward the presser surfaces 21a, thereby burying the tip of the beard in the eye of the needle as is customary. After the needles are pressed, the bar 142 is again moved, further drawing the needles down by the angle 140a formed in its groove acting against the roller 141 of the plate 6. The web holder being in a forward position with its throat at about the back line of the needle which position it assumed as the needles were raised previous to this course. Just before the hook of the needle in this drawing down operation comes to the top of the web holder nib, the web holders are all withdrawn enough to permit the new yarn to pass the web holder nib and take the newly formed kinked yarn below the nib, by preference not drawing the new yarn with the needle hard over the knock over, after which the web holders are brought forward, finishing the operation of forming this kinked yarn into finished loops.

The sinkers 22 throughout the explanation given of this needle movement have remained forward until after the new yarn has been drawn off their lower ends by the needle hooks. At this time they are now withdrawn bodily by the withdrawing bar 26 working against their butts 22c through the action of their lever 27, being caused to go outwardly through the action of their driving lever 30, thereby placing the sinkers in the position shown in solid lines in Fig. 7, after which the bar 26 goes forward, getting in position for its next movement of withdrawing the sinkers.

The action of the going out and the withdrawing of the sinkers just described also takes out with it the dividing bar 24 which at the completion of the sinker withdrawing stroke is raised out of butt contact by the rotation of the flattened shaft 32, again assuming a position as shown in solid lines Fig. 7.

The needles that are to knit are again raised, the web holder throat pushing the head of the previously knit series of loops to beyond the back line of the needle hook, the nib preventing the rising of the new course of loops. This procedure follows throughout the knitting of the stocking.

In portions of the fabric where widening takes place after the needle is drawn down,

instead of the web holders coming in and forming the kinked yarn into loops, they are withdrawn to their extreme outward position away from the needles, as shown in Fig. 7, 5 permitting the stepping out needles to step outwardly with their fabric in their hooks as shown in Fig. 3, snapping by the shallow needle bed wall formed at 1b Fig. 7a. This without the stepping needles losing the accuracy of their gauge due to the construction 10 of the notched plate 67 which keeps the stepping needles in accurate relationship.

Such stepping out movement being caused by the rotation of the gear 93 with its eccentric 94 through the action of the operating bar 95 causing one of the cams 98 fastened to this bar 95 to act to raise one of the levers 39, and through this lever, two of the levers 36, with their levers 34. Preceding this movement 20 the bar 42 or 45 on both sides of the machine center in accordance with whether the inner or outer stepping out needles are functioning at the time, raised the levers 34 with their plates 33 in accordance with any 25 suitable pattern mechanism, so that at the time of the movement of the bar 95, the plate or plates 33 will draw the two sinkers away from the needles to their extreme outward position by acting on the sinker butt 22e, in this 30 manner placing the butt 22d of these two sinkers in such position that on the subsequent operation of knitting in the next course, in which the widened needle 1c Fig. 4 appears for the first time, the sinker jacks 53 or 53a 35 can not cause these two sinkers to kink yarn and as these two sinkers are the sinkers that are on either side of the newly added needle, such newly added needle does not have yarn sunk around its shank as shown in Fig. 4.

10 If the inner stepping out groups of needles are functioning, rod 45 is raised, therefore causing the inner levers 34 to be raised, withdrawing therefore only the two sinkers between the central body wale group of needles 15 and the inner stepping groups of needles, first one side of the center line and then the other, in accordance to the stepping action, rod 45 being only raised previous to the course in which the newly added needle will appear, 20 being then lowered after bar 95 shifted, thereby having stepped out the stepping needles and at the same time through cam 98 operated both levers 39, but only one inner lever 36, the other inner lever 36 will be operated at 25 the return stroke of the bar 95. If the outer stepping out groups of the needles are functioning, rod 42 is raised in place of rod 45 as when the inner groups are functioning, other movements being similar.

30 Upon subsequently knitting such a course the resultant fabric will somewhat resemble Fig. 5 drawing the loops (M) and (N) closely together as the yarn (W) had no kink placed in it and so there will be no surplus of yarn at this point to permit of the forming of an

objectionable eyelet at these places where new needles are added.

In the course in which any newly added needle is to appear for the first time, the sinker dividing bar 24 operates as described previously for plain course knitting and due to the drawing back of the two sinkers as described not being capable of projecting the dividing sinker forming one of these two sinkers, but preceding the next course, the sinker dividing bar 24 through its lever 25 and its driving lever 28 out to an abnormally outward position and through a turning of the flattened shaft 32 operates with the bar 24 upon the butts 22e of the two sinkers that were previously made inactive and which remained inactive for one stroke, bringing these sinkers from their dotted outward position to the solid line position shown in Fig. 7, after which the flattened shaft takes the dividing bar 24 out of butt action. The dividing bar in this last described function has been the agency used to return such sinkers as were made inactive for one course, after which regular knitting continues until another widened position is reached.

To make clear the following detailed description of the operation of knitting the stocking blank as shown in Fig. 6, the needles have been numbered, such numbers being used throughout the following explanation, it being borne in mind that where in this description one needle is spoken of, in fine gauge stockings, this really would be three or four needles, the coarseness being resorted to 95 for simplicity of drawings and explanation.

We are assuming at the commencement of this explanation that the previous stocking has been cast off with the exception of the loops held on body wale needles 24 to 32 inclusive, Figs. 6, 21 and 18, it being understood that all other figures also show the machine in this toe tip knitting position:

After casting off the last stocking and before continuing knitting while at one end of the stroke, the various mechanisms are repositioned, so that they will be in a position as shown in all the mechanical figures, that is, the stepping out needles return as far in toward the center of the machine as they can go, against their stop pins, as shown in Figs. 12 and 14, with the stepping needle jack pin control mechanism slides against their stop pins, as shown in Figs. 17 and 18 and with the control jack 5 picking device, as shown in Fig. 16. In this latter case the two inner picking devices on each side of the center have been picked out once as though widening the first course after (C) course Fig. 6.

These three mentioned devices are all 125 caused to return toward the machine center by the raising of their locking pawls, through the movement of the pattern control bars controlling such pawls. Upon the release of these pawls, the steel tapes with their counter- 130

weights caused all the stepping devices to take their innermost position.

It might be well at this time for the sake of clarity to give a letter to each of the positions that the body wale needles at the ends of the strokes can assume. The (A) position; in this position the needle hook is at about the line of the knock-over, with its jack butt 4b in the groove 6a of the operating plate 6 with the controlling jack 5 down in its low position, all as shown in Fig. 31a. Any needles in such position will be raised and lowered to knit. The (B) position; in this position the needle hook is at about the line of the knock-over with its jack butt 4b withdrawn inside the needle bed wall so as not to be operated by the operating plate 6 with the jack control 5 up in its high position all as shown in Fig. 33a. Any needles in such position will not be raised or lowered to knit but remain idle with their hooks at the knock-over. The (C) position; in this position the needle hook is in its extremely low position with its beard end retracted inside the needle bed walls, with its jack butt 4b withdrawn inside the needle bed walls so as not to be operated by the plate 6, with the jack control 5 down in its low position, all as shown in Fig. 31b. Any needles in such position will not be raised or lowered to knit, but will be in such position as to permit stepping needles to work in their stead.

All the locking pawls that were released to permit the various stepping devices to step outwardly are immediately allowed to again go into ratchet rack tooth contact. All body wale needles before the returning of the stepping needles having become (C) needles with the exception of the center group from 24 to 32 inclusive. The cams 133 operate the stepping needle jack pins Fig. 18, holding into action needles 14 to 17 inclusive and 18 to 21 inclusive on either side of the center group of body wale needles. All other needles are out of action as shown in Figs. 21 and 31. The Fig. 41 shows the left hand cam 133 at this time, which has the same position, by preference, as shown in Figs. 17 and 18. The course (C) is then knitted.

Continuing, by preference, knitting this width in order to knit a separating piece of fabric between the old and new stocking to be later cut off, knitting one last course (C) length having slightly longer loops to facilitate the later looping operation. Upon reaching the end of this (C) stroke, we will suppose the yarn eye is standing at the right hand side of the machine when viewed from the front. The inner stepping needle group on the left hand side of the machine is stepped outwardly one needle through the action of its pawl, while at the same time the stepping needle jack pin slide 118 on the same side of the machine is stepped outwardly the distance of two needles, adding thereby one

needle #22 to those needles active in this stepping needle group. The space between the #32 needle of the body wale groups and the #18 needle of the stepping needle group permits the adding of the #33 body wale needle which was a (C) needle but becomes an (A) needle through the stepping out of the inner left hand picking device 190 and 192 and the subsequent raising and lowering of its control jack 5.

After which yarn is fed from right to left having knitted two more needles at that side of the machine to the left of the center line. With the yarn eye now at the left hand side, the inner stepping group on the right hand side of the machine is stepped outwardly one needle through the action of its pawl while at the same time its stepping needle jack pin slide 119 on the same side of the machine is stepped outwardly the distance of two needles, adding thereby one needle #13 to those needles active in this stepping needle group, the space between the #24 needle of the body wale groups and the #17 needle of the stepping needle group permits the adding of the #23 body wale needle which was a (C) needle but becomes an (A) needle through the stepping out of the inner right hand picking device 190 and 192 and the subsequent raising and lowering of its control jack 5, after which the yarn is fed from left to right having knitted two more needles at that side of the machine to the right of the center line.

This procedure continues either after each course is constructed or with interposed like lengthened courses, depending entirely on how quickly it is desired to widen the fabric, in accordance with the gauge of the machine, until all the body wale needles and all the inner stepping needles have become active having therefore in action at this time, needles 5 to 17 inclusive in the right hand stepping wale group and needles 14 to 42 inclusive in the body wale needles and from 18 to 30 inclusive in the left hand stepping needle group, as shown in Fig. 22. At this time course (D) has been knitted Fig. 6. Included in this course are all the right and left hand inner stepping needles, these needle groups being marked (B') and the complete central wale group being marked (AA).

In these movements the cams 133 or the stepping needle jack pin control slides 118 and 119 have moved two spaces at a time as shown in Figs. 41 to 50 inclusive. The stepping of these cams over a double space was necessary in order to add one needle to the end of their groups as the groups, themselves, were at the same time stepping outwardly one needle space.

At the end of this stroke (D) we will suppose the yarn eye to be standing at the right hand side of the machine when viewed from the front. The stepping needle jack pin con-

trol slides at this time are in a position as shown in Figs. 19, 20 and 50. Before reversing, the cam 133, operating on the left hand side of the machine steps outwardly only one space, through the action of its pawl working in shorter indexed ratched racking teeth than heretofore, thereby putting into action one needle to the left hand side of the machine, this needle being #31, thereby putting the 10 cam 133 in a position as shown in Fig. 51. All the other needles operating as in the previous course. The yarn now feeds from right to left knitting in this course one more needle on the left hand selvage edge of the fabric 15 than on the previous course (D). This same procedure follows, always putting in a needle on the side of the machine farthest removed from the yarn eye, until all the needles in the outer stepping wale groups have been added. 20 These groups of needles are lettered (C) Figs. 21 to 30 inclusive and when they are all in action at this time, course (E) Fig. 6 has been knitted. The needles then in action are shown in Fig. 23. The pin cams 133 are then 25 as shown in Fig. 54, the groups of needles in action on this course (E) being lettered (C—B'—AA—C'—B').

This width of the fabric is knitted on these needles until a point in the fabric has been 30 reached as shown by line (E') Fig. 6. We will now suppose the yarn eye to be standing at the right hand side of the machine when viewed from the front. As this time the left hand outer stepping needle group steps one 35 needle space outwardly, carrying its most outer jack pin to the surface of the place 136, as shown in Fig. 55, thereby keeping all its group needles in action but forming a space between its needle 31 and needle 30 of the inner left 40 hand stepping group permitting the adding of the body wale needle 43. This needle being changed from a (C) to an (A) needle by the stepping out of the outer left handpicking devices 190 and 192 which after being stepped 45 out raise their jack 5 and lower it, thereby causing this needle 43 to be changed from a (C) to an (A) needle. This continues at each side of the machine farthest from the 50 yarn eye with the desired number of like courses knitted in between each widening, until a position is reached in the knitting as shown by line (F) Fig. 6. The pin cam 133 in these courses having moved from Figs. 55 to 58 inclusive, the needle positions at this 55 course (F) being as shown in Fig. 24, the needles in action being numbered 1 to 4 inclusive, 10 to 13 inclusive, 5 to 17 inclusive, 14 to 42 inclusive, 18 to 30 inclusive, 43 to 46 inclusive and 31 to 34 inclusive, the groups of 60 needles in this course being marked (C—a—B'—AA—B'—a—C). The butt arrangement standing at this time is as shown in Fig. 32.

We will suppose the yarn eye at the end of 65 the course to be standing at the right hand

side viewing the machine from the front. From this point on in the knitting, two yarn eyes must be in action at once, as is customary in Cotton frames. The ravel desirable after the course (F) of widened foot course will now be knitted. It is necessary during this portion of the operation to cause the instep needles marked (AA') to become (B) needles, that is to remain with their hooks at about the knock-over with their butt 4b withdrawn so as not to be operated, with their loops in their hooks. This group of needles is composed of the central body wale group of needles numbered from 14 to 42 inclusive and having on each side thereof three of the inner stepping groups of needles. On the right hand side these needles are numbered 15, 16, 17, and on the left hand side these needles are numbered 18, 19 and 20. In order to make these body wale needles inactive with their hooks at the knock-over, the jack control plates 156, 158 and 166 are raised as shown in Fig. 33 and to make the stepping needles that are made inactive with their hooks at the knockover inactive, the stepping needle pin control slides are raised as shown in Fig. 59.

At the commencement of the next knitting operation therefore, the stepping needles 1 to 4 inclusive, the body wale needles 10 to 13 inclusive, the stepping needles 5 to 13 inclusive and 21 to 30 inclusive, the body wale needles 43 to 46 inclusive and the stepping needles 31 to 34 inclusive are active forming two groups, lettered (C—a—B) one on each side of fabric lettered (AA) with yarn being fed to the right hand series and a separate yarn to the left hand series as is customary in knitting full fashioned hosiery on Cotton frames.

The butt arrangement being as shown in Fig. 33. The number of courses desired for foot ravel are knitted with this arrangement after which the needles that were knitting these two ravel stripes cast off their loops during which time the stepping needle jack pin control slides with their cams 133 remain as shown in Fig. 59, the butt arrangement having remained as shown in Fig. 33 and the needle arrangement having remained as shown in Fig. 25. Again we will suppose the yarn eyes to be standing at the right hand side of the machine when viewed from the front.

Before knitting the next portion of the fabric which will form the end of the heel flaps at line (G) knitting with two yarns one for each side of the stocking it is necessary that the outer stepping groups fall inwardly against their stop pins, but before doing so the (a) group of body wale needles numbered 10 to 13 inclusive and 43 to 46 inclusive which were (A) needles must become (C) needles. To do so requires that the entire outer groups of body wale needles be acted upon by the

control jack raising plates 157 and 159. As the needles of these two groups, with the exception of the few that were used as (A) needles in previous courses, are already (C) needles and as the raising of the plates 157 and 159 will make all the needles of these groups temporarily (B) needles with their needle hooks at about the line of the knock-over, it is necessary that the outer stepping groups 10 (C) be taken outwardly beyond the last needle of these body wale groups.

This is accomplished through the operation of the rods 99 and 100 Figs. 7 and 14. These rods move in opposite directions and take 15 the outer stepping needles out beyond the outer body wale group of needles in which position their jack pins are as shown in Fig. 60, their locking pawls locking them in this position permitting the rods 99 and 100 to fall 20 inwardly to their normal position, permitting then the raising of the jack control raising plates 157 and 159 as shown in Fig. 34. In this operation the needles 1 to 9 inclusive and 25 47 to 56 inclusive which were (C) needles become temporarily (B) needles while the needles 10 to 13 inclusive and 43 to 46 inclusive which were (A) needles also become (B) needles, the plates 146 and 148 then coming down as shown in Fig. 35, causing the entire 30 outer body wale groups of needles to become (C) needles, after which the plates 157 and 159 go down as also shown in Fig. 35. After this the outer stepping groups of needles can 35 be released to move inwardly which is accomplished by releasing their locking pawls and permitting their tapes and weights to function. Their pins then assuming the position as shown in Fig. 61, the butt arrangement being then as shown in Fig. 35, after 40 which the stepping needle jack pin control slides with their cam 133 are raised through the endwise sliding of the bar 201 as shown in Fig. 62. This causes only alternate needles to remain in action at this time, therefore 45 only stepping needles are in action and only alternate needles of these groups numbered 2, 4, 6, 8, 10, 14 and 21, 23, 25, 27, 29, 31, 33 as shown in Fig. 26. The yarns then travel 50 from right to left one yarn feeding only to the right hand heel flap and the other yarn feeding only to the left hand heel flap as is customary in full fashioned machines. Before 55 the reverse stroke from left to right, the pin cams 133 on their slides 118 and 119 assume through the endwise sliding of the bar 201 the position shown in Fig. 63, thereby putting into action the needles 1 to 14 inclusive and 21 to 34 inclusive, as shown in Fig. 27, no body wale needle having been in action in the last 60 course nor will there be in this course from left to right.

With the yarn now at the right hand side of the machine viewed from the front, the left hand outer stepping needle group comprising the needles 31 to 34 are now stepped

outwardly one needle space as shown in Fig. 64. Into this space here provided between the needles 30 and 31, the body wale needle 43 is put into action by the left hand outer picking device 190 and 192 which is racked 70 into action over and under the jack control which controls the needle 43 and by raising and then lowering the picking devices making this needle, which was a (C) needle into an (A) needle. The yarn then feeding from right to left. Before reversing the same procedure taking place on the opposite side of the machine, until enough needles have been added to widen the heel flaps for a distance marked (a) comprising as shown in the Fig. 28 the needles 10 to 13 inclusive and 43 to 46 inclusive, at which time the fabric has been produced to a point marked (G') Fig. 6, at which time the stepping needle pins are in a position as shown in Fig. 64, the needle butts being as shown in Fig. 36 and the needles being as shown in Fig. 28. After which sufficient fabric is knitted for the necessary length of the heel lap, the same number of needles remaining in action, after which time the knitting has progressed to the line marked (H) Fig. 6.

We will now suppose the yarn eye standing at the right hand side of the machine when viewed from the front. At this time the needles that form the instep that have been idle with the loops held in their hooks become active. These needles comprise group (AA') shown in Fig. 25, the center portion of them being body wale needles and the outer two portions being inner stepping needles, the body wale needles being (B) needles that must be changed to (A) needles. They are so changed by the lowering of the plates 157 and 158. This is accomplished by the plates 156 and 158 making an abnormally low movement as shown in dotted lines Fig. 37 and by the down movement of the plate 166. The needles in the stepping groups being made active by the lowering through endwise sliding of the bar 201 of the jack pin cam slides, with the cam 133 assuming a position as shown in Fig. 65. At this time, therefore, the needle arrangement is as shown in Fig. 29, at which time the same needles are in action as were in action during the knitting of course (F). The last knitted course (H) is shown in Fig. 28 with the additional needles comprising the instep group. All the needles in action at this time are therefore (C—a—B'—AA—B'—a—C), the butt arrangement being as shown in Fig. 37. The next course to be knitted is course (J) Fig. 6. At about this time the inner body wale needle picking devices are moved into their innermost position through the action of their tapes and weights by the raising out of ratchet rack tooth contact of their locking pawls, getting these devices ready for the toe 125 of the next stocking.

Knitting then continues, knitting the ankle fabric of the desired length with this number of needles in action, until a point is reached where the leg widening is to continue, at 5 which time we will again suppose the yarn eye to be standing at the right hand side of the machine when viewed from the front. The left hand outer group of stepping needles is racked outwardly one needle making a pin 10 arrangement in relation to the cam 133 as shown in Fig. 66, thereby leaving a space between the last body wale needle #46, and the first stepping needle 31. This space must be filled at the next course by the body wale 15 needle 47 which has been up to now a (C) needle. This needle becomes an (A) needle, through the stepping out of the left hand outer picking devices 190 and 192 after which these devices are raised, then lowered, thereby 20 making needle #47 an (A) needle. The yarn then comes from right to left knitting on this added needle.

The above procedure is carried out with any suitable number of like courses in between each widening at both sides of the fabric, widening always when the yarn eye is at the opposite end of the machine traverse, until a line in the fabric marked (K) Fig. 6 is reached. At which time the butt arrangement will be as shown in Fig. 38, the needle arrangement being as shown in Fig. 30, all needles in the machine being in action, forming a group C—*a'*—B'—AA—B'—*a'*—C), after which any length of fabric is knitted 35 that is desired and if a top widening leg is wanted, the same procedure follows that followed in the leg widening, sufficient body wale needles being provided. After which the yarn is fed only traversing far enough 40 to feed to the center group of body wale needles 24 and 32, while the remainder of the needles cast off their loops.

Again supposing the yarn eye to be at the right hand side of the machine when viewed 45 from the front. The control jack raising plates 156, 157, 158 and 159 are raised as shown in Fig. 39, thereby making all body wale needles (B) needles after which the plates 145, 146, 147 and 148 are brought down 50 as shown in Fig. 40 at which time the plates 156, 157, 158 and 159 also go down making all body needles except the center group (C) needles. At this time the outer picking devices move inwardly to their innermost position by raising their locking pawl permitting 55 their counterweights acting through the steel tapes to act, setting these for the new stocking. The plates 145, 146, 147 and 148 being raised to their normal upper position. After 60 which the stepping out needles with their beds move inwardly to their extreme inner position through the raising of their locking pawls, which permits the tapes with their counterweights to function. The cams 133 65 operating the stepping needle jack pins also

move to their innermost position through the raising of their locking pawls which permit the counterweighted tapes to function. When all these movements have taken place, the needles in action will be those shown in 70 Fig. 21 as at the commencement of the toe knitting previously explained with the butt arrangement as shown in Fig. 1 and a plate 133 positioned as shown in Figs. 17, 18 and 41.

While various mechanisms and devices 75 have been shown and described in the foregoing, in order to more clearly explain the working of the principles involved, I wish to point out that I do not intend these detailed mechanisms to in any way limit the 80 scope of this invention, and while en-masse operating needles have been shown, such use is not at all pertinent to the carrying out of the spirit of the invention as these needles could well be operated to function successively. Neither is it necessary to use the type 85 of yarn sinking devices shown, as any devices capable of sinking yarn could be used, and it would even be possible to eliminate entirely the sinkers, as in some types of 90 spring needle knitting machines. It is also not necessary to use the particular type of web holders shown and described as knocking over bits, as now used in full fashioned machines, could be designed in combination 95 with alterations to other element movements.

It would be also possible to be within the spirit of this invention, by completely altering the mechanical features, through the use 100 of latch needles, in place of spring beard needles. In other words, what I have disclosed are basic principles. To disclose them, it was necessary to use some form of mechanisms, but I wish to point out most emphatically, that these mechanisms must not in any 105 way limit the scope of the principles.

What is claimed is:

1. In a flat knitting machine for knitting a wrought stocking blank, a central group of 110 needles, stepping needles on either sides thereof, means for stepping these needles outwardly from the central group, means for adding to the central group of needles as the stepping needles step outwardly with means at the same time for adding needles to the stepping groups.

2. In a flat knitting machine for knitting a wrought stocking blank, a central group of needles with means for increasing the number of needles in this group, with stepping needles on either side of this central group stepping outwardly from the central group as needles are added to the central group and means for stepping the needles outwardly.

3. In a flat knitting machine for knitting a wrought stocking blank, having sinker jacks capable of moving certain of the sinkers a greater or lesser distance than other sinkers and means for actuating the jacks to 120

- positively advance and retract the sinkers.
4. In a flat knitting machine for knitting a wrought stocking blank, having sinkers, a cam cooperating therewith adapted to operate all the sinkers to take one length of loop, and a second cam adapted to cooperate only with certain of the sinkers and acting when rendered operative to cause these sinkers to take a longer length of loop in the same course. 50
5. In a flat knitting machine for knitting a wrought stocking blank, having a slurcock, means for reciprocating it, and means including a tapered gib for causing said slurcock to operate upon its sinker members a greater or lesser amount. 55
6. In a flat knitting machine for knitting a wrought stocking blank, having needles having jacks with butts carried in jack beds with a pin underlying each jack capable of projecting the jack butts beyond the outer face of the beds, the pins being in staggered relation to each other and cam means for actuating the pins. 60
7. In a knitting machine the combination with needles of a stationary needle bed, a stepping needle bed overlying the stationary bed and adapted to move lengthwise thereof to permit the insertion of previously idle needles between the active needles of the two beds to widen the fabric, and webholders cooperating with the needles of both beds. 65
8. In a knitting machine the combination with needles of a stationary needle bed, a stepping needle bed overlying the stationary bed and adapted to move lengthwise thereof to widen the fabric, means for adding to the number of active needles in the stepping needle bed, and means for inserting previously idle needles from the stationary bed between the active needles of the two beds. 70
9. In a knitting machine the combination with spring needles of a stationary needle bed, a stepping needle bed overlying the stationary bed and adapted to move lengthwise thereof, and a single set of webholders adapted to cooperate with the needles in both beds. 75
10. In a knitting machine the combination with spring needles of a stationary needle bed, a stepping needle bed overlying the stationary needle bed and adapted to move lengthwise thereof, the needles of both beds being adapted to cooperate to knit a continuous row of stitches, and a single set of webholders adapted to cooperate with the needles in both beds. 80
11. In a knitting machine the combination with spring needles of a stationary needle bed, a stepping needle bed overlying the stationary bed and adapted to move lengthwise thereof, the needles of both beds being adapted to cooperate to knit a continuous row of stitches, and a single series of sinkers, web-
- holders and presser surfaces for the needles operating in both beds. 85
12. In a knitting machine the combination with needle and cooperating knitting elements of a stationary needle bed, a stepping needle bed overlying the stationary bed and adapted to move lengthwise to permit the replacing of specified needles of one bed by those of the other bed, a set of stationary grooves for registering the active needles accurately with the cooperating elements, and means for stepping the stepping needle bed outwardly snapping the needles from groove to groove with yarn held on the hooks of the stepping needles. 90
13. In a knitting machine the combination with spring needles and cooperating knitting elements of a stationary needle bed, a stepping needle bed overlying the stationary bed and adapted to move lengthwise thereof, the needles of both beds being adapted to cooperate to form a continuous row of stitches, a set of stationary grooves for registering the active needles accurately with the cooperating elements, and means for moving the stepping needle bed with yarn held on the hooks of the stepping needles. 95
14. In a knitting machine the combination with knitting elements of a fixed needle bed, body needles mounted therein, a stepping needle bed overlying the stationary bed and adapted to move lengthwise thereof, needles carried in the stepping needle bed adapted to replace the body needles, and a set of stationary grooves for registering the active needles accurately with the co-operating elements. 100
15. In a knitting machine the combination with spring needles of a stationary needle bed, a stepping needle bed overlying the stationary needle bed and adapted to move lengthwise thereof, the needles of both beds being adapted to cooperate to knit a continuous row of stitches, and a set of stationary grooves for registering accurately the active needles adapted to permit active stepping needles to snap from one groove to the next. 105
16. In a knitting machine the combination with cooperating knitting elements of a stationary needle bed, body needles mounted therein, a stepping needle bed overlying the stationary bed and adapted to move lengthwise thereof, stepping needles mounted therein, and a set of shallow stationary grooves for registering the active needles accurately with the cooperating elements adapted to permit the stepping needles to snap from one groove to another. 110
17. In a knitting machine the combination with needles and cooperating knitting elements of a stationary needle bed, a stepping needle bed overlying the stationary bed and adapted to move lengthwise thereof, the needles of both beds being adapted to cooper- 115
- 120
- 125
- 130

ate to knit a continuous row of stitches, a set of stationary grooves for registering the active needles accurately with the cooperating elements, and a comb secured to the stepping 5 needle bed to support the active needles in this bed.

18. In a knitting machine the combination with cooperating knitting elements of a stationary needle bed, body needles mounted 10 therein, a stepping needle bed overlying the stationary bed and adapted to move lengthwise thereof, stepping needles mounted therein, the needles of both beds being adapted to cooperate to knit a continuous row of stitches 15 and a comb secured to the stepping needle bed to support the active stepping needles.

19. In a knitting machine the combination with knitting elements of a stationary needle bed, body needles mounted therein, a stepping needle bed adapted to move lengthwise 20 of the stationary bed, stepping needles mounted therein, the needles of both beds being adapted to cooperate to knit a continuous row of stitches, a set of stationary 25 grooves for registering the active needles accurately with the cooperating elements, and a comb secured to the stepping needle bed to support the active stepping needles during 30 the movement of the stepping bed to transfer the stepping needles from one to another stationary groove.

20. In a knitting machine the combination with a single series of sinker elements and a presser bar of a stationary needle bed, body 35 spring needles mounted therein, a stepping needle bed overlying the stationary bed and adapted to move lengthwise thereof, stepping spring needles mounted therein, the needles 40 of both beds being adapted to cooperate to knit a continuous row of stitches and a set of stationary grooves for registering the active needles accurately with the sinker elements.

21. In a knitting machine the combination with spring needles of a single series of sinkers and webholders, a sinker bed slotted to receive these elements and having stationary 45 presser surfaces formed on the forward portion of the bed between the slots, a stationary 50 needle bed, a stepping needle bed overlying the stationary bed and adapted to move lengthwise thereof, the needles of both beds being adapted to cooperate to knit a continuous row of stitches, a set of stationary grooves 55 for registering the needles accurately with the cooperating elements, and a presser bar for pressing the beards of the active needles.

22. In a knitting machine the combination with spring needles of a single series of sinkers, a sinker bed slotted to receive these elements and having stationary presser surfaces formed on the forward portion of the bed 60 between the slots, a stationary needle bed, a stepping needle bed adapted to move lengthwise of the stationary bed, the active needles 65

of both beds being adapted to cooperate to knit a continuous row of stitches, a presser bar adapted to flex the needles to close the needle beards against the presser surfaces, and means for operating the presser bar. 70

23. In a knitting machine the combination with spring needles of a single series of sinkers and webholders, a sinker bed slotted to receive these elements and having stationary presser surfaces formed on the forward portion of the bed between the slots, a stationary needle bed, a stepping needle bed adapted to move lengthwise of the stationary bed, the active needles of both beds being adapted to cooperate to knit a continuous row of stitches. 80 means for moving the stepping bed to permit the insertion of additional needles from the stationary bed, mechanism for withdrawing the webholders to permit the moving of the stepping needle bed, and a presser bar for 85 pressing the beards of the active needles.

24. In a knitting machine the combination with needles and cooperating elements of a stationary needle bed, a stepping needle bar overlying the stationary bed and adapted to move lengthwise thereof, the needles of both beds being adjusted to cooperate to knit a continuous row of stitches, a set of stationary grooves for registering the active needles accurately with the cooperating elements, a 90 comb mounted to move with the stepping needle bed to support the active needles mounted in the latter bed, means for retracting the inactive needles in the stationary needle bed out of operative position, and a 95 member secured to the stepping needle bed for holding the inactive needles in the bottoms of their slots.

25. In a knitting machine the combination with the needles of a stationary needle bed, a stepping needle bed adapted to move lengthwise of the stationary bed to permit the replacing of the specified needles of one bed by those of the other bed, means for retracting the inactive needles in the stationary needle bed out of operative position, and a member actuated in timed relation to the movement of the stepping needle bed to hold the inactive needles of the main bed in the bottoms of their slots. 105

26. In a knitting machine the combination with cooperating knitting elements of a stationary needle bed, body needles mounted therein, a stepping needle bed adapted to move lengthwise of the main needle bed, stepping needles mounted therein, the needles of both beds being adapted to cooperate to knit a continuous row of stitches, means for moving the stepping needles into and out of operating position, additional means for moving the body needles into and out of operating position, and single means for actuating the active needles of both beds. 110

27. In a knitting machine the combination with cooperating knitting elements, includ- 125

ing a series of independent sinkers, of a stationary needle bed, body needles mounted therein, a stepping needle bed adapted to move lengthwise of the main needle bed, stepping needles mounted therein, the needles of both beds being adapted to cooperate to knit a continuous row of stitches, a cam bar adapted to actuate the active needles of both beds, means for moving the stepping needles independently into and out of engagement with the cam bar, means for moving the body needles independently into and out of operative engagement with the cam bar, and means for actuating the bar.

28. In a knitting machine the combination with a series of independent sinkers of a stationary needle bed, body needles mounted therein, a stepping needle bed adapted to move lengthwise of the main needle bed,

29. stepping needles mounted therein, the needles of both beds being adapted to cooperate to knit a continuous row of stitches, and a cam bar for actuating the active needles of both beds.

25 29. In a knitting machine the combination with spring needles of a stationary needle bed, a stepping needle bed overlying the main needle bed and adapted to move lengthwise thereof, the needles of both beds being adapted to cooperate to knit a continuous row of stitches, knockover elements adapted to extend between the needles, and means for withdrawing the knockover elements to permit the stepping of the stepping needle bed.

30. In a knitting machine the combination with needles of a stationary needle bed, a stepping needle bed adapted to move lengthwise of the stationary bed to widen the fabric, and means for moving the stepping needle bed comprising a rack formed on the stepping needle bed, a pawl to engage the rack, and means for actuating the pawl.

31. In a knitting machine the combination with needles of a stationary needle bed, a stepping needle bed adapted to move lengthwise of the stationary bed, the needles of both beds being adapted to cooperate to knit a continuous row of stitches, means for imparting a step by step movement to the stepping needle bed comprising a rack formed on the stepping needle bed, a pawl to engage with the rack, means for actuating the pawl, and cam means for normally holding the pawl out of engagement with the rack.

32. In a knitting machine the combination with needles of a stationary needle bed, a stepping needle bed overlying the stationary bed and adapted to move lengthwise thereof, the needles of both beds being adapted to cooperate to knit a continuous row of stitches, means tending yieldingly to hold the stepping needle bed in its inmost position overlying the stationary bed, means for imparting a step by step movement to the stepping needle bed comprising a rack formed on the

stepping needle bed, a driving pawl to engage with the rack, a stop pawl for holding the stepping needle in the position to which it is advanced by the driving pawl, and cam means for normally holding the pawl out of engagement with the rack. 70

33. In a knitting machine the combination with spring needles of a stationary needle bed, a stepping needle bed overlying the stationary bed and adapted to move lengthwise thereof to permit the insertion of previously idle needles between the active needles of the two beds, the needles of both beds being adapted to cooperate to knit a continuous row of stitches, a set of sinkers adapted to cooperate with the needles in both beds, and means for holding the sinkers adjacent the newly inserted needle out of operation. 75

34. In a knitting machine the combination with spring needles of a stationary needle bed, a stepping needle bed adapted to move lengthwise of the stationary bed to permit the insertion of previously idle needles between the active needles of the two beds, the needles of both beds being adapted to cooperate to knit a continuous row of stitches, a single series of sinkers adapted to cooperate with the needles in both beds, and devices mounted on the stepping needle bed adapted to hold the adjacent sinkers temporarily out 90 of operation upon the insertion of a new needle. 95

35. In a knitting machine the combination with spring needles of a stationary needle bed, a stepping needle bed overlying the stationary bed and adapted to move lengthwise of the stationary bed to permit the insertion of previously idle needles between the active needles of the two beds, the needles of both beds being adapted to cooperate to knit a continuous row of stitches, and means for preventing the newly added needle from knitting during the first course or courses. 100

36. In a knitting machine the combination with needles of a plurality of stationary needle beds, stepping needle beds adapted to fill the gaps between the stationary beds and to move lengthwise of the stationary beds for widening the fabric, the needles of the several beds being adapted to cooperate to knit a continuous row of stitches, and means for adding to the number of active needles in the stationary beds to widen the fabric. 110 115

37. In a knitting machine the combination of a stationary central group of needles, a stationary group of needles spaced to each side of the central group, and groups of stepping needles overlying the central group and adapted to step outwardly into the spaces between the stationary groups of needles, 120 125 the needles of all the beds being adapted to cooperate to knit a continuous row of stitches.

38. In a knitting machine the combination of a stationary central group of needles, a stationary group of needles spaced to each 130

side of the central group, and groups of stepping needles overlying the central group and adapted to step outwardly into the spaces between the stationary groups of needles.

39. In a knitting machine the combination of a stationary central group of needles, a stationary group of needles spaced to each side of the central group, two groups of stepping needles overlying the central group and adapted to step outwardly into the spaces between the stationary groups of needles, and additional groups of stepping needles overlying the spaced stationary needles and adapted to step outwardly beyond these stationary groups.

40. In a knitting machine the combination of a stationary central group of needles, a stationary group of needles spaced to each side of the central group, and groups of stepping needles overlying the central group and adapted to move lengthwise into the spaces between the stationary groups of needles to permit the replacing of specified needles of the stepping group by those of the central stationary group.

41. In a knitting machine the combination of a stationary central group of needles, a stationary group of needles spaced to each side of the central group, groups of stepping needles overlying the central group and adapted to move lengthwise into the spaces between the stationary groups of needles to permit the replacing of specified needles of the stepping group by those of the central stationary group, and additional groups of stepping needles overlying the spaced stationary needles and adapted to step outwardly beyond these stationary groups to permit the replacing of specified needles of the latter stepping groups by those of the spaced stationary groups.

42. In a knitting machine the combination of a stationary central group of needles, a stationary group of needles spaced to each side of the central group, groups of stepping needles overlying the central group and adapted to move lengthwise into the spaces between the stationary groups to permit the replacing of specified needles of the stepping groups by those of the central stationary group, and additional groups of stepping needles adjacent the first-mentioned stepping group, the active needles of all the groups being adapted to cooperate to knit a continuous row of stitches.

43. In a knitting machine the combination of a stationary needle group, a stepping needle group overlying the stationary group and adapted to cooperate to knit a continuous row of stitches, means for stepping the stepping group lengthwise of the stationary group, and a picker device for rendering active additional needles of the stationary group comprising a vertically movable arm

and picker members movable horizontally in the arm.

44. In a knitting machine the combination of a stationary needle group, a stepping needle group overlying the stationary group and adapted to cooperate therewith to knit a continuous row of stitches, butts for actuating the needles, means for stepping the stepping group lengthwise of the stationary group but provided to move the needles into and out of active position, and a picker device for rendering active additional needles of the stationary group comprising a butt contact member movable lengthwise of the needle group to engage with the required butt, and an arm on which the butt contact member is slidably mounted movable lengthwise of the needles.

45. In a knitting machine for knitting a wrought stocking blank, a central group of needles, and a stepping group on either side thereof, with another stepping group outside of the first stepping group, the stepping groups being movable toward and away from the central group, and means for adding active needles to the central group and to the first stepping group.

46. In a knitting machine the combination with cooperating knitting elements of a stationary needle bed, body needles mounted therein, a stepping needle bed overlying the stationary bed and adapted to move lengthwise thereof, stepping needles mounted therein, the needles of both beds being adapted to cooperate to knit a continuous row of stitches, and a comb for registering the stepping needles and movable therewith.

47. In a knitting machine, the combination with a single series of sinker elements and a presser element of a stationary needle bed, body spring needles mounted therein, a stepping needle bed overlying the stationary bed and adapted to move lengthwise thereof, stepping needles mounted therein, the needles of both beds being adapted to cooperate to knit a continuous row of stitches, and a set of stationary grooves for registering the active needles accurately with the sinker elements.

48. In a knitting machine, the combination with spring needles of a stationary needle bed, a stepping needle bed adapted to move lengthwise of the stationary bed, the active needles of both beds being adapted to cooperate to knit a continuous row of stitches, stationary pressing surfaces, a presser bar adapted to flex the needles of both beds to close the needle beards against the presser surfaces, and means for operating the presser bar.

49. In a knitting machine, the combination with cooperating knitting elements of a stationary needle bed, body needles mounted therein, a stepping needle bed adapted to move lengthwise of the main needle bed, step-

ping needles mounted therein, the needles of both beds being adapted to cooperate to knit a continuous row of stitches, and a single means for actuating the active needles of both beds.

50. In a knitting machine, the combination with cooperating knitting elements, including a series of independent sinkers, of a stationary needle bed, body needles mounted therein, a stepping needle bed adapted to move lengthwise of the main needle bed, stepping needles mounted therein, the needles of both beds being adapted to cooperate to knit a continuous row of stitches, a single operating means adapted to actuate the active needles of both beds, means for moving the stepping needles independently into and out of engagement with the said operating means, and means for moving the body needles independently into and out of operative engagement with the said operating means.

51. In a knitting machine having a series of collectively operated needles, the combination with the needles, of a series of yarn feeding sinkers, means for advancing and retracting the sinkers adapted to advance the sinkers successively during the knitting of each course, and means for causing the sinkers associated with the widening needles to remain inoperative during the sinking of the yarn for the widening course.

52. In a knitting machine having a series of needles, knitting elements cooperating therewith comprising a series of yarn feeding sinkers, means for advancing and retracting the sinkers including sinker operating jacks movable into and out of operating position, and means acting automatically to move the jacks controlling the sinkers associated with the widening needles to inoperative position to cause the said sinkers to remain inoperative during the knitting of a widening course.

53. In a knitting machine having a series of needles, the combination with the needles, of knitting elements comprising a series of yarn feeding sinkers, means for advancing and retracting the sinkers comprising sinker operating jacks movable from operative to inoperative position, and means acting automatically to move the jack controlling sinkers associated with the widening needles to render the said sinkers inoperative during the knitting of a widening course.

54. In a knitting machine, the combination with needles, of a stationary needle bed, a stepping needle bed overlying the main needle bed and adapted to move lengthwise thereof, the needles of both beds being adapted to cooperate to knit a continuous row of stitches, knitting elements cooperating with the needles including a series of web holders operated collectively in unison, and means for causing a group of said web holders asso-

ciated with the stepping needles to remain inoperative in retracted position while the remaining web holders are collectively moved during the knitting of the course.

55. In a knitting machine, the combination with needles, of a stationary needle bed, a stepping needle bed overlying the main needle bed and adapted to move lengthwise thereof, the needles of both beds being adapted to cooperate to knit a continuous row of stitches, knitting elements cooperating with the needles including a series of web holders operated collectively in unison, and means acting when inoperative to cause the web holders associated with the stepping needles to remain in a full retracted position during the knitting of a course.

In testimony whereof I have signed my name to this specification.

CERTIFICATE OF CORRECTION.

Patent No. 1,876,722.

September 13, 1932.

MAX C. MILLER.

It is hereby certified that error appears in the printed specification of the above numbered patent requiring correction as follows: Page 12, line 90, for "rascd" read "raised"; page 22, line 89, claim 24, for "bar" read "bed"; and line 92, for "adjusted" read "adapted"; page 24, line 101, claim 46, for "steep-
ing" read "stepping"; and that the said Letters Patent should be read with these corrections therein that the same may conform to the record of the case in the Patent Office.

Signed and sealed this 29th day of August, A. D. 1933.

(Seal)

M. J. Moore.
Acting Commissioner of Patents
